UNITED STATES PATENT OFFICE.

HAAKON A. MARTIN, OF WHITESTONE, NEW YORK, ASSIGNOR TO THE
NATIONAL CASH REGISTER COMPANY, OF DAYTON, OHIO.

SLIP PRINTING AND REGISTERING MACHINE.

1,399,391.

Specification of Letters Patent.

Patented Dec. 6, 1921.

Application filed December 28, 1918. Serial No. 268,727.

To all whom it may concern:

Be it known that I, HAAKON A. MARTIN, a citizen of the United States, residing at Whitestone, Long Island, in the county of 5 Queens and State of New York, have invented certain new and useful Improvements in Slip Printing and Registering Machines, of which I declare the following to be a full, clear, and exact description.

10 This invention relates to improvements in cash registers, and the like, the primary object being to devise a mechanism which is adapted for use in grocery stores, meat markets, departmental stores and other analogous lines of business. The present invention is also very well adapted to be used in connection with any system where duplicate slips are used, as the machine herein is designed to issue sales slips in duplicate, although it is not intended to limit the scope 20 of this invention to printing and issuing sales slips as the machine is also adapted to print upon and issue other papers, such as express receipts, bills of lading, etc., but for convenience the present form of embodiment is illustrated and described as printing and issuing duplicate sales slips. Another object of the invention is to provide a machine 25 with two totalizers, a transaction totalizer and a grand totalizer, the former for accumulating totals of each transaction of every kind, and the latter for accumulating the total of all cash and received on account 30 transactions.

35 Another object is to provide the machine with an improved form of printing mechanism controlled by manipulative devices, so that the transaction totalizer may be moved bodily from its connection with its actuating 40 mechanism in order that the total amount upon said totalizer may be printed therefrom upon the sales slips or other papers.

Another object is to provide the machine with two consecutive number mechanisms, 45 one adapted to print the consecutive number upon the record strip, and the other adapted to print the consecutive number upon the sales slip; so that the records upon said strip and slips may be compared.

50 A further object is to provide the machine herein with an autographic feature associ-

ated with the sales slip or other papers as issued by the machine.

Another object is to provide the machine with a drawer releasing mechanism so arranged that it is operated to release the drawer only when a total is taken from the transaction totalizer.

A still further object of the invention is to provide the machine with an interlocking device of such a character and so manipulated that the clerk's initial must be printed upon the record strip and sales slips for each and every transaction.

With these and incidental objects in view, 65 the invention consists in certain novel features of construction and combination of parts the essential elements of which are set forth in appended claims, and a preferred form of embodiment of which is hereinafter 70 described with reference to the drawings, which accompany and form part of the specification.

Of said drawings:

Figure 1 is a front end elevation of the 75 improved registering mechanism and operating handle (partly broken away), the cabinet therefor being shown in section and partly broken away.

Fig. 2 is a rear end elevation of the 80 improved registering mechanism, the cabinet and drawer release mechanism being removed.

Fig. 3 is a vertical sectional view taken on line 3—3 of Fig. 1 and looking in the direction indicated by the arrows.

Fig. 4 is a detail view illustrating the operating handle release and stop mechanism and showing a part of the locking mechanism for the slip printer lever.

Fig. 5 is a vertical sectional view taken on line 5—5 of Fig. 1 and looking in the direction indicated by the arrows.

Fig. 6 is a detail top plan view of the 95 grand totalizer, the framework therefor being partly broken away.

Fig. 7 is a vertical sectional view taken on line 7—7 of Fig. 1 and looking in the direction indicated by the arrows.

Fig. 7a is a detail view of one of the 100 transaction slip printer wheels showing the turn to zero pawl.

Fig. 8 is a detail view of the grand totalizer illustrating a part of the transfer mechanism.

Fig. 9 is a detail view of a part of the mechanism for feeding the sales slip.

Fig. 10 is an end view of the mechanism illustrated in Fig. 9 and also showing the gear for driving said mechanism.

Fig. 11 is a vertical sectional view taken on line 11—11 of Fig. 1 and looking in the direction indicated by the arrows.

Fig. 12 is a detail view of the consecutive number device for printing on the record strip and a part of the mechanism for operating said device.

Fig. 13 is a detail view illustrating the locking mechanism for the clerk's initial actuator (shown partly broken away) and also illustrating a part of the interlocking mechanism, for the amount and transaction actuators, and its relation with the clerk's initial actuator.

Fig. 14 is an end view of the locking mechanism illustrated in Fig. 13, the clerk's initial actuator and interlocking mechanism being removed.

Fig. 15 is a detail view of the mechanism for engaging the transaction totalizer with the actuator and also illustrating the alining device and a part of the inking device for the transaction printing mechanism.

Fig. 16 is a detail view of the mechanism for controlling the inking device for the transaction printing mechanism.

Fig. 17 is a fragmentary view partly in top plan and partly in horizontal section and illustrating the autographic mechanism.

Fig. 18 illustrates the original of a sample duplicate sales slip as issued by the improved registering mechanism.

Fig. 19 is a fragmentary view showing the mechanism for feeding the record strip and printing thereon.

Fig. 20 is a detail view illustrating a part of the mechanism for restoring the transfer arms of both totalizers.

Fig. 21 is a fragmentary view illustrating the mechanism for gripping the sales slip and feeding it.

Fig. 22 is a detail view showing a part of the mechanism for restoring the actuators and operating levers to their normal positions.

Fig. 23 is a fragmentary front elevation of the cabinet showing the inscriptions thereon, the glass which makes the record strip visible, and also illustrating the position of the totalizing, amount, clerk's initial, transaction, and slip printer levers.

Fig. 24 illustrates a sample of a portion of the record strip printed by the machine.

Fig. 25 is a detail view of the transfer mechanism of the grand totalizer.

Described in general terms the machine herein comprises a plurality of manipula-

tive devices consisting of a transaction lever, a clerk's initial lever, and four amount levers which are operated to differentially position actuators associated therewith, and which simultaneously position type wheels to print the character of transaction, clerk's initial and amount of transaction upon a record strip adapted to receive such printing and which is fed a given distance after each printing operation. The actuators are automatically held in alinement until the record print has been taken from the type wheels.

The operating mechanism comprises a train of gears, driven by a crank handle, which imparts movement to two main drive shafts, that carry cams for operating the various elements of the machine.

There are two totalizers, a grand totalizer and a transaction totalizer. The grand totalizer is arranged to be engaged with the amount actuators for every cash and received on account transaction, so that the amounts of said transactions may be accumulated upon said totalizer as the actuators are being restored to their home position. The engagement of this totalizer is controlled by the transaction actuator and lever, so that for charge, paid out and no sale transactions said totalizer is not engaged with the amount actuators; therefore, nothing is accumulated thereupon for these transactions. The transaction totalizer is so arranged that it is rocked into engagement with the amount actuators for each and every operation of the machine, so that the total amount of all items comprising any one transaction may be accumulated thereupon. A manipulative device is provided so that this totalizer may be bodily moved from its connection with the machine, and the total thereon printed upon a sales slip, after which said totalizer is returned to its normal position and the amount thereon cleared so that the total for a subsequent operation of the machine may be accumulated thereupon.

Mounted upon the transaction totalizer shaft are two type wheels, one of which is arranged to be engaged with the transaction actuator, and the other arranged to be engaged with the clerk's initial actuator, so that when a total amount for any transaction is accumulated upon the transaction totalizer, the character of such transaction and the clerk's initial will be printed upon the sales slip simultaneous with the printing of the amount. These two type wheels are restored to their normal position and cleared at the same time that the transaction totalizer is restored to normal position and cleared.

Also mounted upon the transaction totalizer shaft are three date type wheels which are set manually so that the date is printed upon the sales slip with each transaction.

An interlocking mechanism, a part of which is controlled by manipulative devices and a part controlled automatically, is provided so that the operator is compelled to

- 5 first manipulate the clerk's initial lever before either the transaction lever or any of the amount levers can be manipulated, and so that after the clerk's initial lever has been once set it cannot be moved backward 10 until the proper time, which is after the record has been printed, and then it is done automatically. This always insures the printing of the clerk's initial upon the record strip and sales slip for every transaction that takes place.

As before stated the machine is provided with two consecutive number mechanisms, which are controlled by manipulative means so that every time a total is printed from the 20 transaction totalizer said consecutive number mechanisms are each advanced one and the numbers thereon are printed upon the record strip and the sales slip. The consecutive number mechanism which prints upon 25 the record strip prints the same number opposite the amount of each item comprising any one transaction but is advanced one, as mentioned above, for every transaction. Due to the fact that the clerk's initial 30 and the consecutive number are printed upon the record strip and sales slip for every transaction, the proprietor may easily compare any transaction printed upon said record strip with the sales slip bearing the 35 same consecutive number so that if the amounts are not the same, as they should be, the proprietor will immediately know which clerk made a mistake.

As before stated the machine herein is 40 designed to issue a duplicate sales slip. Said slip is fed from a supply roll (not shown) through the machine from back to front and is guided by paper chutes. The paper passes between an impression roll and an electro, 45 carried by a cylinder. The lines and slip form are printed by said electro. The paper is provided with feeding holes along its edges and is engaged by pins on two disks that are revolved by manipulative means so 50 that the paper is extruded from the machine. After being extruded the slips are torn off and resemble the sample slip illustrated in the drawings.

The drawer releasing mechanism is controlled by manipulative devices and operated to release the cash drawer only when a total is printed from the transaction totalizer which is also simultaneous with the issuing of the slip.

55 To print a total from the grand totalizer the operator pulls down on a manually operated lever which extends through the cabinet. This causes the grand totalizer to be rocked, so that the type, which are on 60 the periphery of the counter wheels of said

totalizer, will engage the record strip, whereby the amount which has been accumulated on said totalizer is printed upon said record strip.

This operation does not turn the totalizer to zero as this must be done by a separate key.

Referring now to the drawings in detail in which like reference numerals designate similar parts throughout the various figures, 75 it will be seen that the mechanism herein is inclosed by a suitable casing or cabinet 25 (Figs. 1, 3, 7, 17, and 23). The mechanism is supported by vertical parallel walls 26 (Figs. 1, 2, 17, and 19) and 27 (Figs. 1, 2, 3 80 and 17) which are secured to a horizontal base 28 (Figs. 1, 2, 3 and 5). The base 28 is mounted upon and secured to a cabinet 29 that encloses a cash drawer 30 (Figs. 1 85 and 3).

Operating mechanism.

The mechanism which imparts movement to the main drive shaft, and as is best shown in Figs. 1, 2, and 3, comprises a pinion 31 90 loosely mounted upon a stud 32 carried by the wall 27. Meshing with the pinion 31 is a gear 33 secured to a horizontal shaft 34 rotatably mounted in bearings in the walls 26 and 27. Meshing with the gear 33 is a gear 35 95 rotatably mounted, and held by any suitable means, upon a stud 36 (Figs. 1 and 3) carried by the vertical wall 27. A gear 37 rigidly secured to a cam shaft 38 meshes with the gear 35. Rotatably mounted upon 100 the stud 32 is a sleeve 39 (Figs. 1, 2 and 3) to which is rigidly secured a crank handle 40 (Fig. 1). The sleeve 39 and crank handle 40 are held on the stud 32 by means of a screw 41 as illustrated in Fig. 1. 105

Before the crank handle 40 can be revolved in the operative or clockwise direction to drive the train of gears, shown in Figs. 1, 2 and 3, it is necessary to give said handle a slight retrograde movement. When 110 the crank handle 40 is moved slightly in the inoperative direction, just mentioned, it will cause the pinion 31, through the engagement of a tenon 42 (Figs. 1 and 3), integral with the sleeve 39, with a mortise 43 cut in a hub 115 44 integral with the gear 31, to be moved slightly in a counter-clockwise direction (Fig. 3). This movement will, through the train of gears illustrated in Fig. 3, cause the cam shaft 38 to be rotated in a clockwise 120 direction. This slight clockwise movement of the cam shaft 38 (Figs. 3 and 4) causes a disk 45, secured fast to said shaft, to also be rocked in a clockwise direction, which allows an arm 46, integral with a forked lever 47, 125 to be disengaged from a notch 48 in the periphery of the disk 45. The forked lever 47 is loosely mounted upon a stud 49 carried by the vertical wall 27 as illustrated in Figs. 1, 2, 3 and 4. The disengagement of the end 130

46 of the forked lever 47, from the notch 48 is effected by a spring 50 (Figs. 1 and 4) that is strained between the said lever and a stud 51 that is carried by the vertical wall 5 27 and which causes said lever 47 to be rocked counter-clockwise until it strikes the stud 51 (Figs. 1, 3 and 4).

After the crank handle 40 has been released, as just described, it is given two revolutions in a clockwise direction (Fig. 3). The ratio of the pinion 31 to the gear 33 is two to one, so that by giving the crank handle 40 (Fig. 1) two clockwise revolutions 10 (Fig. 3) the gear 33 will be revolved once in a counter-clockwise direction, which will cause the shaft 34 to be revolved likewise as the said gear is fast upon this shaft. The gears 33, 35 and 37 all have a ratio of 15 one to one, therefore the counter-clockwise revolution of the gear 33 will rotate the gear 35 clockwise, and the gear 37 counter-clockwise, thereby causing the cam shaft 38 to receive said counter-clockwise rotation, as it will be remembered the gear 37 is fast to 20 this shaft.

During the latter part of the second revolution of the crank handle 40, which is also the latter part of one counter-clockwise revolution of the cam shaft 38, an arm 52 (Figs. 30 2, 3 and 4) engages one end 53 of the forked lever 47. The arm 52 is mounted loose upon the cam shaft 38, and lies against the disk 45 and in the same plane with the end 53 of the forked lever 47, and has its rear edge 54 35 held against a stud 55 that is carried by the disk 45. This is accomplished by a spring 56 strained between said arm and a stud 57 also carried by the disk 45 and causes the arm 52 to be revolved with said disk. During 40 the latter part of the counter clockwise revolution of the disk 45, as mentioned above, the arm 52 engages the end 53 of the forked lever 47. This causes the arm 52 to stop until the stud 57, which it will be remembered 45 is carried by the disk 45, strikes a front edge 58 of the arm 52. The disk 45 and arm 52 now act as a single unit and cause the forked lever 47 to be rocked clockwise until the end 46, thereof, engages the notch 48 50 of the disk 45. This prevents the crank handle 40 from being turned farther than its home position.

The differential mechanism.

55 The machine herein is not provided with a key-board for controlling the differential positioning of the actuators, therefore each of the actuators is provided with a lever that extends through the cabinet so that said 60 actuators may be manually positioned for accumulating amounts upon the totalizers and for positioning the type wheels to print commensurate with said amounts.

This differential mechanism comprises 65 four amount actuators 59 (Figs. 1, 2 and 7),

rotatably mounted upon the shaft 34. Slidably mounted upon the side of each of the four amount actuators 59 and having a circumferential movement thereon, are two segmental members 60, (Figs. 1, 2 and 7) 70 and 61 (Figs. 1 and 7) that are provided with teeth 62 and 63 respectively. These segmental members 60 and 61 are mounted on the actuators by means of four headed studs 64, carried by said members, which fit within slots 65 that are in the said actuators. The function of the segmental members 60 is to position the amount type wheels and to accumulate amounts upon the totalizer, which will be hereinafter described. The 75 function of the segmental members 61 is to accumulate amounts upon the transaction totalizer which will also be hereinafter described. of transaction will be set upon the printers and so that the amount will be accumulated upon the totalizers, the operator moves the clerk's initial lever 74 (Fig. 23) up until the 5 pointer 79, thereon, is opposite the character which represents the clerk making the transaction. The transaction lever 70 (Figs. 11 and 23) is moved up until the pointer 79, thereon, is opposite the inscription representing the kind of transaction which is to be made. The amount levers 66 (Figs. 7 and 23) are positioned likewise until the pointers 79, thereon, are opposite the integers which represent the amount of the 10 item.

The alining and restoring mechanism.

The mechanism for alining the operating levers, actuators, and segmental members 20 thereon, until the totalizers have been engaged with said segmental members, and for alining the type wheels until the record print has been taken therefrom, comprises, four pawls 80 (Figs. 2 and 7) loosely mounted upon a horizontal shaft 81 that is rotatably mounted in bearings in the vertical walls 26 and 27. The pawls 80 are in the same plane with the amount actuators 59 and are laterally spaced by their respective hubs 82 30 (Fig. 2). The ends 83 (Fig. 7) of the pawls 80 are held in engagement with V-shaped notches 84, formed in the actuators 59 which are integral with the amount levers 66, by coil springs 85 (Figs. 2 and 7) strained between said pawls and a rod 86 that is carried by the vertical walls 26 and 27, as is illustrated in Fig. 7. Loosely mounted upon the shaft 81, and in the same plane with the clerk's initial actuator 71, and transaction 40 actuators 67, are two pawls 87 (Figs. 2 and 11, and 13). The ends 88 of the pawls 87 are held in engagement with V-shaped notches 89 Fig. 11, formed in the actuators 71 (Fig. 1) and 67 (Figs. 1 and 11), 45 which are integral with the clerk's initial lever, and the transaction lever, respectively, by coil springs 90 (Figs. 2 and 11) that are strained between said pawls and the rod 86.

50. While the levers 66, 70 and 74 are being positioned the pawls 80 and 87 are rocked back and forth on the shaft 81, by the action of the V-shaped notches 84 and 89 on the ends of said pawls and by the springs 85 and 55 90 (Figs. 7 and 11), until the desired position has been set.

After the levers 66, 70 and 74 have been set to differentially position the actuators and segmental members thereon, the ends 83 60 and 88 of the pawls 80 and 87 respectively, are locked in engagement with the V-shaped notches 84 and 89 of said actuators respectively, by a horizontal rod 91 (Figs. 7 and 11), carried by two parallel arms 92 (Figs. 65 2, 7 and 11) that are fast upon a shaft 93,

and which lies against an edge 94 (Figs. 7 and 11) of the pawls 80 and 87. The rod 91 is normally held against the edge 94 of the pawls 80 and 87 by a spring 95 (Figs. 2 and 5) that is strained between a stud 96, 70 carried by the vertical wall 26, and an arm 97 which is fast upon the shaft 93, it being remembered that the arms 92 which carry the rod 91 are also fast upon the shaft 93.

At the beginning of the first cycle of the 75 machine a square stud 98, carried by a disk 99 that is secured to the cam shaft 38 (Figs. 2 and 5) is moved directly beneath the part 971 of the arm 97 and prevents oscillation of the arm until the high portion 100 (Fig. 80 5) of the disk 99 engages a stud 101 carried by the arm 97 whereupon movement is prevented and the arm cannot be oscillated until the totalizers, which will be hereinafter described, have been rocked into engagement 85 with the segmental members on the actuators and until the type wheels have printed the amount upon the record strip. This causes the rod 91 to be held against the edges 94 of the pawls 80 and 87 so that the operating 90 levers cannot be manipulated.

The arm 97 is cut away at 102 (Fig. 5) and the disk 99 is so formed at 991 that when the pawls 80 and 87 are rocked back and forth, as previously described, there will 95 be a clearance for the arm 97 and the stud 101 during their downward movement, which it will be remembered is occasioned by the rod 91 being engaged with the pawls 80 and 87.

In order to prevent the clerk's initial lever 74 from being manually restored to its normal position after said lever has once been set, the machine herein is provided with a device which comprises a pawl 103 (Figs. 11, 13 and 14), loosely mounted upon the shaft 93 and held in engagement with the notch 89 of the actuator 71 by means of a compression spring 104 which lies between the pawl 103 and an arm 105 (Fig. 13) that 105 is also loosely mounted upon the shaft 93. The arm 105 carries a stud 106 upon which is mounted an anti-friction roller 107 (Fig. 13) which engages a cam race 108 in a disk 109 that is fast upon the cam shaft 38. 110

Should any one attempt to move the clerk's initial lever 74 and actuator 71, integral therewith, in a clockwise direction (Fig. 13) they would not be able to do so because the pawl 103 is so positioned that it will lock 120 tight in the notch 89 thereby preventing the said lever from any retrograde movement after it has once been set. When the lever 74 is being positioned, as previously described, the pawl 103 will simply bob in and out of the notches 89. The configuration of the race 108 is such that at the proper time, and before the levers 66, 70 and 74 are automatically restored to their normal positions, the arm 105 is rocked in a clockwise direc- 125 130

tion (Fig. 13) thereby causing the pawl 103, through a pin 110, carried by the arm 105, which engages a slot 111 in the pawl 103, to also be rocked in a clockwise direction. This 5 movement is sufficient to disengage the pawl 103 from the notch 89 in the actuator 71 so that said actuator and the clerk's initial lever 74 may be automatically restored to their normal position at the proper time.

10 After the totalizers have been engaged with the actuators and before the operating levers and actuators are automatically restored to their normal positions it is necessary to unlock the pawls 80 and 87 and to re- 15 move them entirely from the notches 84 and 89 in the actuators 59, 67 and 71 respectively. This is accomplished by means of a horizontal rod 112 (Figs. 2, 7 and 11) which is carried by an arm 113 (Figs. 2 and 7) and a 20 lever 114 (Figs. 2 and 11) that are fast upon the shaft 81. Pivotaly mounted to the lever 114 at point 115 (Fig. 11) is a pitman 116 which has its lower end bifurcated at 117 to surround the cam shaft 38. Projecting 25 laterally from the pitman 116 is a stud 118 which carries an anti-friction roller 119 that engages a cam race 120 in a disk 121 fast upon the cam shaft 38.

The configuration of the cam race 120 is 30 such that during the first half of the revolution of the disk 121, the pitman 116 will be raised and will cause the lever 114 and the arm 113 to be rocked in a clockwise direction (Figs. 7 and 11). This movement 35 is sufficient to cause the horizontal rod 112 carried by said arm and lever to engage portions 122 and 123 of the pawls 80 and 87 respectively, and to rock said pawls clockwise and thereby disengaging the ends 83 40 and 88 thereof, from the V-shaped notches 84 and 89 in the actuators 59, 67 and 71.

At the proper time, and after the operating levers and actuators have been automatically restored to their zero position, which 45 will be hereinafter described, the cam race 120 causes the pitman 116 to be lowered. This movement will rock the arm 113 and the lever 114, it being remembered that both 50 said arm and lever are fast upon the shaft 81, in a counter-clockwise direction which will release the rod 112 from the projections 122 and 123 of the pawls 80 and 87 respectively, and allow the coil springs 85 and 90 to rock said pawls counter-clockwise 55 so that the ends 83 and 88 thereon, will engage the V-shaped notches 84 and 89 of the actuators 59, 67 and 71.

The mechanism for restoring the actuators 59, 67 and 71 to their zero positions 60 after they have been differentially positioned by the levers 66, 70 and 74, to set up the amount, clerk's initial, and character of transaction, respectively, comprises, a horizontal shaft 124 (Figs. 1, 7, 11 and 22) that 65 is carried by a lever 125 (Figs. 1, 7 and 22),

and a lever 126 (Figs. 1 and 11) that are mounted loose upon the shaft 34. Pivotaly attached to the lower portion 127 of the lever 125 (Figs. 1, 7 and 22) is a link 128 which is provided with a slot 129 to receive 70 the cam shaft 38. Pivotaly mounted to the lower portion 130 of the lever 126 (Figs. 1 and 11) is a link 131 which is also provided with a slot (not shown) to receive the cam shaft 38. The link 128 is provided 75 with two laterally projecting studs 132 and 133 (Figs. 2 and 22) which carry anti-friction rollers 134 and 135, respectively. The rollers 134 and 135 engage the peripheries of two plates 136 and 137, respectively, fast upon the shaft 38 and which together form a double plate cam. The link 131 is also provided with two laterally projecting studs 138 and 139 (Fig. 2) each carrying 80 an anti-friction roller 140 and 141 respectively. The rollers 140 and 141 engage with the peripheries of two plates 142 and 143 (Fig. 2) respectively, which are fast upon the cam shaft 38 and which together form a double plate cam. The actuators 59, 67 and 71 are each provided with a radial slot 144 (Figs. 7 and 11) to receive the shaft 124. When the double plate cams, above described, are given a revolution by the cam shaft 38, the timing of said double plate 90 cams being identical, the links 128 and 131, at the proper time, will be moved rearward and downward (Figs. 7, 11 and 22). This movement of the links 128 and 131 will cause the levers 125 and 126 to be rocked in 95 a clockwise direction, thereby causing the shaft 124 to engage the ends 145 (Figs. 7 and 11) of the slots 144, which, it will be remembered were differentially positioned 100 when the operating levers were set to record a transaction upon the machine; and to restore the actuators 59, 67 and 71 to their zero or home positions. The segmental members 60 and 61 (Fig. 7), will also be 105 restored to their zero position, it being remembered that they are carried by the actuators 59. The operating levers 66, 70 and 74 (Fig. 23) being integral with the actuators 59, 67 and 71 will also be restored 110 to their zero position.

After the levers and actuators have been restored to their zero position, as above described, the links 128 and 131 are moved forward and upward, by the double plate cam, which causes the levers 125 and 126 115 to be rocked counter-clockwise thereby causing the shaft 124 to be returned along the slot 144, to its normal position.

Transfer mechanism.

The transfer mechanism for the four lower elements of the grand totalizer, to be hereinafter described is best shown in Figs. 1, 2 and 7, and comprises, three transfer arms 146 that are loosely mounted upon a 120 130

horizontally disposed shaft 147, rotatably mounted in bearings in the vertical walls 26 and 27, said transfer arms being laterally spaced on the shaft 147 by hubs 148 (Fig. 1). These transfer arms 146 are held in their normal position by arms 149 (Figs. 2 and 7), which lie in the same plane with the transfer arms 146, and which are provided with V-shaped notches 150 (Fig. 7), and are held in engagement with said transfer arms by springs 151 (Figs. 2 and 7) strained between said transfer arms and the arms 149. Coöperating with each of the transfer arms 146 is a lever 152 (Figs. 1 and 7) pivotally mounted at point 153 to the three highest amount actuators 59. Projecting laterally from each of the levers 152 is a pin 154 (Fig. 7) that fits within slots 155 formed in the segmental members 60. The pins 154 are held in engagement with the ends of the slots 155 (Fig. 7) by springs 156 (Figs. 1 and 7) that are strained between the levers 152 and studs 157, carried by the actuators 59. Integral with each of the levers 152 is a formed portion 158 that cooperates with a projection 159 integral with each of the transfer arms 146.

When a counter wheel passes from 9 to zero, a pin 160 (Fig. 7), carried by said counter wheel, engages a projection 161 on the transfer arm 146 and rocks said arm counter-clockwise (Fig. 7) so that it will be cammed out of the upper V-shaped notch 150 in the arm 149, and engage the lower V-shaped notch in said arm.

At the proper time, and after the actuators 59 have been automatically restored to their zero actuators, as previously described, said actuators are moved one step, 40 in a clockwise direction (Fig. 7), past the said zero position. The last mentioned movement of the actuators 59 is occasioned by the engagement of a pin 162 (Fig. 7), carried by the forward end of bell cranks 45 163, which engages a projection 164 that is integral with each of the actuators 59. The bell cranks 163 are loosely mounted upon the shaft 93 and laterally spaced thereon by their hubs 165 (Fig. 2). The lower arm 50 of each of the bell cranks 163 is provided with an antifriction roller 166 (Fig. 7) which fits within a cam race 167 formed in the disks 168. The disks 168 are fast upon the cam shaft 38, therefore when said shaft 55 is revolved, as previously described, the disks will be also revolved whereby the bell cranks 163 will, through the race 167 and roller 166, be rocked in a counter-clockwise direction thereby causing the stud 162 to 60 engage the portion 164 of the actuators 59 and rock said actuators one step past their zero position. The slot 155 in the segmental member 60, is so formed that when the actuators 59 are rocked clockwise, as 65 previously described, the segmental mem- bers will be carried with said actuators and the two will move as a unit. When the transfer pawls 146 have been rocked counter-clockwise, by the pin 160, as previously described, the projection 159 on the said transfer arms will be rocked away from the formed portion 158 of the levers 152, so that when the actuators 59 are moved one step past their zero position, as previously described, the segmental member 60 will be 70 allowed to travel this one extra step thereby causing one to be added to the counterwheel of the next higher denomination.

Should the transfer arm 146 not be tripped, the projection 159 thereon will 80 course remain in the position as shown in Fig. 7. When the actuators 59 are rocked one step past their zero position, and the projection 159 remains as shown in Fig. 7, the formed portion 158 of the lever 152 will 85 engage the projection 159 of the transfer arm 146 and cause said lever to be pivoted about this point between the formed portion 158 and projection 159 while said lever is being carried in a clockwise direction by the 90 actuators 59. This will cause the pin 154 on the lever 152 to slide along the slot 155 in the segmental member 60 so that said member will not move the extra step with the actuator but will remain back so that 95 there will be nothing added upon the counter wheel of the next higher denomination.

The transfer mechanism for the elements of the transaction totalizer, to be hereinafter described, is best viewed in Figs. 1 and 7, 100 and comprises, three transfer levers 169 (Figs. 1 and 7) that are loosely mounted upon a horizontally disposed shaft 170 carried by bearings in the vertical walls 26 and 27. The transfer levers 169 are held in their 105 normal position by pawls 171 Fig. 7 which are held in engagement with a notch 172, which is in the lower portion of the lever 169, by springs 173 strained between said pawls and said transfer levers. The pawls 171 are mounted upon a horizontal shaft 174 that is rotatably mounted in bearings in the vertical walls 26 and 27. Coöperating with each of the transfer levers 169 is a lever 175 (Figs. 1 and 7) pivotally mounted 110 to the actuators 59 at point 176. Projecting laterally from the lever 175 is a pin 177 which fits within a slot 178 formed in the segmental member 61, and is normally held in engagement with the end of said slot, as 115 is viewed in Fig. 7, by a spring 179 strained between said lever 175 and stud 180 carried by the actuator 59. Each of the levers 175 is provided with a formed portion 181 that normally lies very close to the extreme upper 120 end 182 of the transfer levers 169 and is best shown in Fig. 7. When one of the transaction counter wheels passes from 9 to zero, a pin 183 carried by said counter wheels engages the projection 184 of the transfer 125 130

levers 169 and causes said transfer lever to be rocked counter-clockwise so that the pawl 171 will be disengaged from the notch 172 and will engage another notch 185 which is 5 also in the transfer levers 169.

When the transfer lever 169 has been tripped, as is described above, there will be no interference between the formed portion 181 of the lever 175 and the upper end 182

- 10 of the said transfer lever, when the actuators 59 are moved one step past the zero position as previously described, the segmental member 61 will therefore be carried one step farther so that one will be added
- 15 to the counter wheel of the next higher denomination. Should the transfer lever 169 not be tripped, the formed portion 181 will stop against the end 182 of the lever 175 and said lever will pivot about this point
- 20 practically the same as does the lever 152 previously described in the grand totalizer mechanism, so that the pin 177 will slide along the slot 178 of the segmental member 61 thereby causing said segmental member
- 25 to remain in the position shown in Fig. 7 so that nothing will be added to the counter wheel of the next higher denomination.

During the first part of the next operation of the machine all displaced transfer arms 30 and transfer levers will be automatically restored to their normal positions. This mechanism comprises, a horizontal rod 186 (Figs. 2 and 7) that is carried by parallel arms 187 fast upon a shaft 188 that is rotatably 35 mounted in bearings in the vertical walls 26 and 27. Also fast upon the shaft 188 is an arm 189 (Figs. 2 and 7) to which is pivotally mounted a link 190, the lower end of which is pivotally mounted to an arm 40 191 fast upon the shaft 174. Rigidly secured to the shaft 174 are two parallel arms 192 that carry a horizontal rod 193. Also fast upon the shaft 174 is an arm 194 (Figs. 1, 7 and 20) to which is pivotally mounted 45 the forward end of a pitman 195 which is bifurcated at 196 (Fig. 20) to surround the cam shaft 38. The pitman 195 carries an anti-friction roller 197 which fits within a cam race 198 formed in a disk 199 fast upon 50 the cam shaft 38, and as is best viewed in Figs. 2 and 20.

When the disk 199 (Figs. 2 and 20) is given a revolution by the cam shaft 38, it will cause the arm 194, through the pitman 55 195, roller 197 and cam race 198, to be rocked in a clockwise direction (Figs. 7 and 20) thereby causing the shaft 174 and the arms 192, mounted thereon to receive a counter-clockwise revolution, it being remembered 60 that the arms 192 and 194 are fast upon said shaft. This movement is sufficient to cause the rod 193 to engage the lower edge of the transfer levers 169, and rock said levers in a clockwise direction so that the 65 pawls 171 will be disengaged from the

notches 185 and engage the notches 172, which is the normal position for said transfer levers. When the shaft 174 is rocked counter-clockwise, as above described, the arm 191 will be rocked likewise, it being remembered that this arm is also fast upon said shaft. This will cause the shaft 188 (Fig. 7), through the link 190 and arm 189 to be rocked in a counter-clockwise direction. This counter-clockwise movement of the shaft 188 will rock the arms 187, it being remembered that the arms 187 are fast upon the shaft 188, in a counter-clockwise direction so that the rod 186, carried by said arm, will engage the lower edge of the transfer arms 146 (Fig. 7) and cause said arms to be rocked clockwise so that they will be disengaged from the notches 160 of the arms 149 and will engage the notches 150 of said arms, this being the normal position of said 85 transfer arms.

Totalizers.

As previously stated the machine herein is provided with two totalizers. One grand 90 totalizer for accumulating all cash and received on accounts amounts, and one secondary or transaction totalizer for accumulating all cash, received on account, charge and paid out amounts for every operation 95 of the machine. The last mentioned totalizer is automatically turned to zero during each operation of the machine. The grand totalizer will be described first. It comprises, four counter wheels 200 (Figs. 2, 6, 7, 8 and 100 11), having fastened to the side of each, a pinion 201 arranged to mesh with the teeth 62 which, it will be remembered, are integral with the segmental members 60. Three counter wheels 202 (Fig. 6) comprise the 105 overflow for the counter wheels 200. These seven counter wheels are rotatably mounted upon a shaft 203 (Figs. 2, 6, 7 and 8) carried by parallel plates 204, 205 mounted fast upon a horizontal shaft 206 (Figs. 1, 7 and 11) 110 which is rotatably mounted in bearings in the vertical walls 26 and 27. The counter wheels 200 are held in alignment by pawls 207 (Figs. 2, 6 and 7) that are held in engagement with the pinions 201 by springs 208 strained between said pawls and a rod 209 carried by the plates 204 and 205, as best illustrated in Figs. 6 and 7. These pawls 207 are loosely mounted upon a shaft 210 (Figs. 6 and 7) that is also carried by the plates 120 204 and 205. The transfer mechanism for the four counter wheels 200 has already been described.

The means for transferring from the four counter wheels 200 to the overflow counter wheels 202, as illustrated in Figs. 6 and 8, comprises, a disk 211 secured to the side of the pinion 201 carried by the counter wheel 200 of the highest denomination. This disk 211 has one gear tooth 212 arranged to mesh 130

with a pinion 213 fast upon one end of a sleeve 214 (Figs. 6 and 8) loose upon the shaft 210. Fast to the other end of the sleeve 214, is a pinion 215 (Fig. 6) that 5 meshes with a pinion 216 (Fig. 1) fast to the side of the counter wheel 202 of the lowest denomination. The pinions 213 and 215 are held in alinement by a spring pressed pawl 217 (Figs. 6 and 8) that engages the teeth 10 of the pinion 213. This pawl is loosely mounted upon a shaft 218 carried by the plates 204 and 205.

When the counter wheel 200, of the highest denomination, passes from 9 to 0 the 15 gear tooth 212, integral with the disk 211, engages the pinion 213 (Fig. 8) thereby causing said pinion to be moved one step, which will also move the pinion 215 (Fig. 6) one step, it being remembered that both 20 pinions 213 and 215 are fast upon the same sleeve. The pinion 215 being in engagement with the pinion 216 (Fig. 6) that is fast upon the lower denomination counter wheel 202, of the overflow counter will cause said 25 pinion 216 and counter wheel 202 to be moved one step thereby adding one to said counter wheel. The transfer mechanism for the remaining wheels 202 is substantially the same as that just described.

30 As before stated the counter wheels of the grand totalizer are only engaged with the actuators during "cash" and "received on account" transactions, while during "charge," "paid out" and "no sale" transactions said totalizer is held out of engagement with the actuators. Means for controlling the engagement and disengagement of said grand totalizer will now be described. It comprises a plate 219 (Figs. 1, 2 and 11) 35 loose upon the shaft 206, and lies adjacent the plate 205. Projecting laterally from the plate 219 is a stud 220 (Figs. 2 and 11). An arm 221 (Figs. 2 and 11) loose on the shaft 81 is provided with a V-shaped notch 222 that 40 is held against the stud 220 by a spring 223 that is strained between said arm and a disk 224 that is carried by a horizontal shaft 225, so that the plate 219 is normally held against any oscillation. Pivottally mounted to the 45 plate 219 at point 2261, is the upper end of a link 226 (Figs. 1 and 11) that is formed in the center so that the lower end of said link, which is pivotally mounted to another link 50 227 (Figs. 1 and 11), will lie adjacent the last mentioned link. This last mentioned link 227 is provided with a slot 228 (Fig. 11) so that said link may be reciprocated upon the shaft 34. Pivottally fastened to the link 226 at point 229 is the upper end of a bell crank 55 230 (Fig. 11) that is also provided with a slot 231 so that said bell crank may also be reciprocated upon the shaft 34. The lower end of the bell crank 230 is so formed that it 60 will lie adjacent the transaction actuator 67. This portion of the bell crank 230 carries an

anti-friction roller 232 that engages a slot 233 formed in the actuator 57. The link 227 is held in its normal position (Fig. 11) by a disk 234, fast upon the shaft 34, and which engages an anti-friction roller 235 carried 70 by said link.

Integral with the lever 114 (Fig. 11), which, it will be remembered, is loose upon the shaft 81, is an arm 236 that carries an anti-friction roller 237 which fits within a 75 slot 238 in the plate 205.

For a cash or received on account transaction, the transaction lever 70 (Figs. 11 and 23) is moved upward so that the pointer 79, thereon, is opposite either the cash or received on account inscription (Fig. 23) on the cabinet 25. This movement of the lever 70 will cause the actuator 67 to be rocked counter-clockwise (Fig. 11), as it will be remembered the actuator 67 85 and transaction lever 70 are integral. The movement of the actuator 67 will cause the bell crank 230 to be moved downward so that the upper portion of its elongated slot 231 will engage the shaft 34. This is occasioned by a step 239 in the slot 233 which, is in the actuator 67 and which engages the roller 232, carried by the bell crank 230. The downward movement of the bell crank 230 causes the link 226 to be 90 pulled downward, which, in turn, rocks the plate 219 counter-clockwise (Fig. 11) until a portion 240, thereon, engages a stud 241 carried by the plate 205. The downward movement of the link 226 also causes the 95 link 227 to be rocked slightly in a counter-clockwise direction which positions the roller 235, thereon, nearer the top of the high portion of the disk 234. The counter-clockwise movement of the plate 219, above 100 described, causes the pin 220, thereon, to be disengaged from the V-shaped notch 222 of the lever 221 and to be engaged in another V-shaped notch 242 which is also in the lever 221. This movement of the plate 219 105 also causes a portion 243, integral therewith, to be positioned in front of and slightly below the center of the roller 237 on the arm 236. When the portion 243 is 110 so positioned the rear edge 244, thereof, and an edge 245 on the plate 205 form a slot, as it will be remembered the plate 219 lies adjacent the plate 205.

At the proper time, and after the amount 115 actuators have been manually positioned, the arm 236 is rocked clockwise, by means of the pitman 116 which, it will be remembered, is fastened to the lever 114 integral with said arm. It will also be remembered that the pitman 116 receives its upward 120 movement by the engagement of the roller 119, thereon, with the cam race 120 in the disk 121 which is secured to the cam shaft. When the arm 236 is rocked clockwise, as 125 described above, the roller 237, thereon, 130

will engage the edge 244 and will cause the plate 219 to be rocked in a counter-clockwise direction. This will cause the plate 205, by the engagement of the projection 240 with the pin 241 (Fig. 11) to be rocked counter-clockwise until said roller lies in that part of said slot which is between edges 246 and 247 that are on the plates 205 and 219, respectively, and which form a neutral portion of said slot. This movement of the plates 205 and 219 is sufficient to cause the pinions 201 of the counter wheels 200 (Fig. 7), which, it will be remembered, are carried by the frames 204 (Fig. 7) and 205 (Fig. 11), to be engaged with the teeth 62 that are integral with the segmental members 60, carried by the amount actuators 59.

At the proper time, and after the amount actuators 59 and segmental members, thereon, have been automatically restored to their zero position, the arm 236 is rocked counter-clockwise, which causes the roller 237, thereon, to engage the edge 245 of the plate 205 and rock said plate and shaft 206 in a clockwise direction, it being remembered that the plate 205 is fast to said shaft. This movement will also cause the plate 219, through the engagement of the stud 241, carried by the plate 205, with the projection 240 on the plate 219, to also be rocked in a clockwise direction.

During the first part of the operation of the machine, the disk 234, which, it will be remembered, is fast upon the shaft 34, is revolved in a clockwise direction, (Fig. 11). When the plate 219 is rocked counter-clockwise by the engagement of the roller 237, on the arm 236, with the edge 244, integral with the said plate, the link 226 will be moved downward and will cause the link 227 to be rotated counter-clockwise. As the link 226 is being moved downward it is also being rocked clockwise around its pivot 2261, thereby causing the link 227 to be moved rearward while it is being oscillated counter-clockwise as above mentioned. The rocking movement of the link 226 is caused by the bell crank 230, which, it will be remembered, is pivoted to said link at the point 229, and as said bell crank has been moved downward by the step 239 in the slot 233 of the actuator 67, it cannot move downward any more therefore it will rock counter-clockwise when the link 226 is moved downward, as above described, which will cause the link 226 to be rocked clockwise as above described.

At the proper time, and after the totalizers 60 have been disengaged as previously described, the disk 234 will engage the roller 235 on the link 227 and cause said link to be moved forward. The forward movement of the link 227 will rock the link 226 counter-clockwise which will cause the bell crank 230

to be rocked in a clockwise direction. The roller 232 that is carried by the bell crank 230 has ample clearance in the slot 233 for all of the above described rocking movements of said bell crank.

From the above description it will be readily seen that the plates 204 (Fig. 7) and 205 (Fig. 11) are in their normal position, but the portion 240 of the plate 219 still lies against the stud 241 which, it will be remembered is carried by the plate 205.

When in this position the stud 220, carried by the plate 219, is engaged in the V-shaped notch 242 of the lever 221. Means for restoring the plate 219 to its normal position 80 will now be described. It comprises a cam 248 (Fig. 11) that is fast upon the shaft 147. This shaft 147 is given a clockwise oscillation, by means which will be herein-after described, so that said cam 248 will 85 be rocked in the same direction, thereby causing said cam to engage a pin 249 carried by the plate 219, which causes said plate to be rocked in a clockwise direction until an edge 250 engages a pin 251 that is carried 90 by the plate 205. This is the normal and home position of said plate 219. During this restoration of the plate 219 the link 226 is moved upward which will cause the link 227 to be oscillated in a clockwise direction, 95 which will leave it in the position shown in Fig. 11. The upward movement of the link 226 will also cause the bell crank 230 to be moved upward and left in the position as shown in Fig. 11.

During a charge, paid out or no sale transaction, the slot 233 in the transaction actuator 67 is so formed that when the transaction lever 70 is set for either one of the above transactions, the roller 232 on the bell 105 crank 230 will remain on high portion 252 of the slot 233. This will cause the bell crank 230 to remain in the position as shown in Fig. 1 and therefore the link 226 will not be moved, so that the plate 219 will also remain in the position shown in Fig. 11. At the proper time during the operation of the machine, as previously described, the arm 236 is rocked in a clockwise direction and as the plate 219 has not been moved the roller 237, carried by the arm 236, will engage a slot 253 that is formed in the plate 219, and keep said plate from any oscillation. This will also cause the edge 250 of the plate 219 to remain in engagement with the pin 251 110 carried by the plate 205, whereby the said plate 205 is kept from any oscillation therefore the totalizers which, it will be remembered, are carried by the plate 205 and another plate 204 will be kept from engaging 115 the actuators.

The secondary or transaction totalizer, as mentioned above, is for the purpose of accumulating the total amount for every transaction of the machine herein. This mecha- 130

nism will now be described and comprises, four counter wheels 254 (Figs. 1, 7 and 15) that are rotatably mounted on a sleeve 255 (Figs. 7 and 15) that is loose upon a shaft 256. The shaft 256 is rotatably mounted in bearings in two parallel plates 257 (Figs. 1 and 5) and 258 (Figs. 1, 7 and 15) which are fast upon a shaft 259 (Figs. 1, 5, 7, 11 and 15) that is rotatably mounted in bearings in the vertical walls 26 and 27. Secured to the side of each of the counter wheels 254 is a pinion 260 (Figs. 1, 7 and 15) which is arranged to mesh with the teeth 63, which, it will be remembered, are integral 15 with the segmental members 61 that are carried by the amount actuators 59. The pinions 260 are normally out of engagement with the teeth 63 of the segmental members 61.

20 The counter wheels 254 are held in alignment by spring pressed pawls 261 (Figs. 1, 7 and 15) that are engaged with the pinions 260. These pawls are loosely mounted upon a horizontal shaft 262 that is rotatably 25 mounted in bearings in parallel plates 257 and 258. The pawls 261 are normally locked in engagement with the pinions 260 by means of a rod 263 (Figs. 1, 7 and 15) which engages a portion 264 of the pawls 261. The rod 263 is carried by a pair of parallel bell cranks 265 (Fig. 1) and 266 (Figs. 1, 7 and 15) that are mounted fast upon the shaft 262. The means for controlling the locking and releasing of the pawls 261 comprises, a link 267 (Figs. 1, 7 and 15) which is pivotally fastened to the bell crank 266 at point 268 (Figs. 7 and 15). The link 267 is provided with an elongated slot 269 (Fig. 15), through which passes the 30 shaft 259. The link 267 is held in its normal position by a lever 270, (Figs. 7 and 15) having integral therewith a segmental portion 271, the true periphery of which engages a pin 272 that is carried by the extreme lower end of the link 267, thereby holding said link in its normal position. Pivotally fastened to the lever 270 at point 273 is a pitman 274 which is bifurcated at 45 275 to surround the cam shaft 38. The pitman 274 carries an anti-friction roller 276 (Fig. 15) that engages a cam race 277, formed in a disk 278 fast upon the cam shaft 38. At the proper time, and after the transaction totalizer has been engaged with 50 the segmental members on the actuators, the pawls 261 are released or unlocked so that the totalizer wheels may be operated. This is accomplished by the disk 278 and cam race 277 which causes the pitman 274 to be 55 moved forward (Fig. 7) which, in turn, causes the lever 270 to be rocked in a clockwise direction. This movement of the lever 270 causes a pin 279, carried by said lever, to engage a projection 280, integral with the 60 link 267, and cause said link to be moved up- 65 ward. The upward movement of the link 267 rocks the bell cranks 265 and 266 in a clockwise direction, both bell cranks being fast on the shaft 262. This will cause the rod 263 to be moved away from the portion 264 of the pawls 261, thereby allowing said pawls to be rocked back and forth by the action of the pinions 260 on the said pawls. The configuration of the cam race 277 is such that the pawls 261 will immediately be unlocked and will remain unlocked until after the transaction totalizer has been turned to zero, which will be hereinafter described, and then the pawls are locked and remain locked until the totalizer has been engaged with the actuators, and unlocked again after the engagement of the actuators and said totalizer and they are kept unlocked until the actuators have been restored and until after the transferring which was previously described, has taken place,

20 The means for engaging and disengaging the transaction totalizers with the actuators will now be described, and comprises, two 90 rearwardly extending arms 281 (Fig. 1) and 282 (Figs. 1, 7 and 15) which are integral with the plates 257 and 258, respectively. The arms 281 and 282 are provided with anti-friction rollers 283 (Fig. 1) and 284 (Figs. 1, 7 and 15) respectively, which engage cam races 285 formed in disks 286 fast upon the shaft 34.

At the proper time and after the actuators and segmental members have been differentially positioned, the cam races 285 in both of the cams 286 being identical, will cause the arms 281 and 282 to be moved toward the shaft 34. The arms 281 and 282 being integral with the plates 257 and 258 105 respectively, will rock said plates in a counter-clockwise direction a sufficient amount to cause the pinions 260 of the counter wheels 254, to be engaged with the teeth 63 of the segmental members 61. While the 110 transaction totalizer is thus engaged with the segmental members above mentioned, the actuators 59, which carry said segmental members, are restored to their normal position. The restoration of said actuators 59 115 and segmental members 61 causes the amount which was set up on the said actuators, to be added upon the transaction totalizer.

As before mentioned, the transaction totalizer is turned to zero after every complete 120 transaction which means every time a total is printed from the transaction totalizer. This takes place at the beginning of the next operation of the machine and clears said totalizer of the amounts which have been accumulated thereupon during the previous operation. The means for accomplishing this result will be now described and comprises, a disk 287 (Figs. 1 and 5) that is fast 125 upon the sleeve 255, which it will be re- 130

membered is rotatably mounted upon the shaft 256 and upon which are mounted the totalizer wheels. The disk 287 is formed with lateral projections 288, integral therewith, which mesh with teeth 289 (Figs. 1 and 5) of a segment 290 that is loose upon the shaft 34. Integral with the segment 290 is a segment 291 having teeth 292 that mesh with teeth 293 of a segment 294 fast upon one end of a sleeve 295 (Figs. 2 and 5) loose upon a shaft 93. Integral with the segment 294 is an arm 296 which carries an anti-friction roller 297 that coöperates with the periphery of a plate cam 298 fast upon the cam shaft 38. Fast upon the cam shaft 38 is an arm 299 (Figs. 2 and 5) that engages a pin 300, carried by the arm 296, and which acts as a stop for the segment 294 in its normal position as illustrated in Fig. 5.

At the proper time, and before the transaction totalizer has been engaged with the actuators, the cam plate 298 and the arm 299, being fast on the cam shaft 38, will be revolved in a clockwise direction, (Fig. 5) and cause the arm 296 to be rocked in a clockwise direction, by the engagement of a projection 301 (Figs. 2 and 5), that is integral with and projects from the arm 299, which engages the roller 297, thereby forcing the said roller against the periphery of the plate 298 and causing the arm 296 to be rocked clockwise as mentioned above. The segment 294 will also be rocked clockwise, it being remembered that said segment is integral with the arm 296, which in turn, causes the segments 291 and 290 to be rotated slightly in a counter-clockwise direction. The counter clockwise movement of the segment 290 will cause the disk 287 to be rotated slightly in a clockwise direction. The disk 287 being fast upon the sleeve 255 will rotate said sleeve slightly in a clockwise direction which movement is for the purpose of and is sufficient to allow pawls 4151 that are carried in the counter wheels 254, to fall in a notch 302 (Figs. 7 and 15) that is formed in the sleeve 255. As the disk 298 and arm 299 continue their movement in a clockwise direction the roller 297 on the arm 296 is forced between the projection 301 and the periphery of said cam plate 298. The cam plate periphery is so formed that it will engage the roller 297 on the arm 296 and cause said arm and segment 294, integral therewith, to be rocked in a counter clockwise direction which will cause the segments 291 and 290 to be rocked in a clockwise direction. This clockwise movement of the segment 291 will move the segment 290 likewise, as the last mentioned segment is integral with the first mentioned segment. This movement will cause the disk 287, through the engagement of the teeth 289 with the projections 288 on the said disk, to be rotated in a counter clockwise direction which will also rotate the sleeve 255 (Figs. 7, 7^a and 15) in a counter clockwise direction thereby causing the notch 302, in said sleeve, to pick up the pawls 4151 in each of the counter wheels 254 whereby said counter wheels will be rotated in a counter clockwise direction which will restore them to their zero position. When the said counter wheels reach their zero positions they are stopped by the engagement of the pin 183, carried by each of said counter wheels, with a stop pawl 303 (Figs. 7 and 15) that is fast upon the shaft 262 and which is rocked in a clockwise direction until the end, thereof, lies directly beneath the pin 183. The clockwise movement of the pawl 303 is occasioned by the upward movement of the link 267 (Fig. 15) which it will be remembered is moved by the engagement of the pin 279 with the projection 280 on the said link. The pin 279 is moved upward by the pitman 274 which is controlled by the cam race 277 of the disk 278 that is fast upon the cam shaft 38. When the segment 290 has reached its farthest downward position and the transaction totalizer has been returned to zero, said segment is held in this position by means of a pin 305 (Fig. 5) carried by a lever 306 that is loose upon the shaft 170. The pin 305 is held in engagement with a V-shaped notch 307, formed in the segment 290, by means of a spring 308 that is stretched between the lever 306 and a horizontal shaft 309 that is rotatably mounted in bearings in the vertical walls 26 and 27.

After the transaction totalizer has been turned to zero and disengaged from the actuators, the segments 290 and 291 are restored to their normal position by means, which comprises an arm 310 (Figs. 2 and 5) that is fast upon one end of the sleeve 295, it being remembered that the segment 294 is fast to the other end. Pivotally fastened to the arm 310 is the upper end of a pitman 311 (Figs. 1, 2 and 5) that is bifurcated at 312 to surround the shaft 259. From the above description it will be readily seen that when the segment 294 was rocked in a counter clockwise direction, that the arm 310 would be rocked at the same time and in the same direction. This rocking movement of the arm 310 will cause the pitman 311 to be moved forward and downward until an anti-friction roller 313, carried by said pitman, lies against the shorter radial periphery 314 (Fig. 5) of a disk 315 that is fast upon the shaft 259. To restore the segments 290 and 291 to their home positions the disk 315, being fast upon the shaft 259 is rocked in a clockwise direction, by means which will be hereinafter described, so that the pitman 311 will be forced upward and rearward by the engagement of a higher radial periphery 316, of the disk 315, with the roller 313 carried by said pitman. This

movement will cause the arm 310 to be rotated in a clockwise direction. The arm 310 and segment 294 being fast to the same sleeve, said segment will be rotated clockwise which will rotate the segments 290 and 291 in a counter clockwise direction thereby restoring said segments 290 and 291 to their normal position.

10 *Printer.*

The mechanism whereby the character of transaction, clerk's initial, and the amount of transaction will be printed upon a record strip will now be described. Four amount type wheels 317 (Figs. 1 and 7) that are loosely mounted upon the shaft 206, and spaced laterally thereon by their hubs 318 (Fig. 1). Secured to the side of each of the type wheels 317 is a pinion 319 (Figs. 1 and 7) that meshes with the teeth 62 of the segmental members 60. A clerk's initial type wheel 320 (Fig. 1) is also mounted loose upon the shaft 206, and has fastened to its side a pinion 321 meshing with the teeth (not shown) integral with the clerk's initial actuators 71. Also loose upon the shaft 206 is a transaction type wheel 322 (Fig. 1) that has secured to its side a pinion 323 that meshes with the teeth 68 integral with the transaction actuator 67. These six type wheels 317, 320 and 322, above described, are differentially positioned by the actuators 59, 67 and 71, when said actuators are differentially positioned by the setting 35 of the amount levers 66, clerks initial lever 74 and transaction lever 70 respectively. Due to the fact that the above described type wheels are always in engagement with the actuators, said type wheels will be restored to their normal position at every operation of the machine simultaneous with the restoring of the actuators, as previously described.

As before stated, the machine herein is provided with a consecutive number counter that is adapted to print on the record strip. Said consecutive number counter will now be described. It comprises four counter wheels 324 (Figs. 1, 11 and 12) that are 45 rotatably mounted upon the shaft 206. These counter wheels 324 are provided with type on their peripheries for printing on the record strip. This counter is of the usual step by step type, therefore only a brief description of its operation will be given herein. The counter is advanced one step each complete operation of the machine by means of a spring pressed pawl 325 (Fig. 12) loosely mounted on a stud 50 326 (Fig. 12) carried by parallel arms 327 (only one arm being shown in Fig. 12) that are fast upon the shaft 147. Also fast upon the shaft 147 is an arm 328 (Figs. 5 and 12) that has pivoted to its extreme end the upper end of a link 329 (Figs. 1, 5 and 12)

the lower end of which is pivotally mounted to the disk 315 (Fig. 5) which it will be remembered is fast to the shaft 259. When the shaft 259 is rotated in a clockwise direction (Fig. 5) the disk 315 is revolved 55 likewise and causes the link 329 to be raised, which, in turn, causes the arm 328 to be rotated clockwise. The arm 328 being fast upon the shaft 147 will cause said shaft and the arms 327 to be rotated in a clockwise direction, whereby the spring pressed pawl 325 will be moved forward so that the projections 330, integral with the said pawl, will engage a ratchet 331 that is fastened to the side of each of the counter wheels 324, 60 and move said ratchet in a clockwise direction (Fig. 12) for a distance of one tooth. The counter wheels 324 and ratchet 331, thereon, are prevented from any retrograde movement by pawls 332 (Figs. 1 and 12) 65 that are held in engagement with the teeth of the ratchet 331 by means of springs 333 that are strained between said pawls and a stud 334 carried by the side frame 26.

As before stated, the machine herein is 70 provided with a record strip. The mechanism for carrying and feeding said record strip will now be described. It comprises, a plate 335 (Figs. 1, 2, 11 and 19) provided with a hub 336 (Fig. 2) pinned to a shaft 75 337 which is rotatably mounted in bearings in the vertical walls 26 and 27. Projecting laterally from the plate 335 is a stud 338 upon which is mounted a supply roll 339 (best illustrated in Figs. 2, 7, 19 and 11). 80 The plate 335 also carries another stud 340, upon which is mounted a plate 341 (Figs. 1 and 7), said plate being held upon said stud by means of a screw 342 (Fig. 1). Rotatably mounted in bearings in the plates 85 335 and 341 is a shaft 343 (Figs. 7 and 11) upon which is rotatably mounted a sleeve 344 which carries, fast thereto, a resilient roller 345. Another resilient roller 346 is fast upon a sleeve 347 (Figs. 7 and 11) 90 that is rotatably mounted upon a shaft 348 also carried by the plates 335 and 341. The record strip 350 is fed from the rear of the supply roll 339 downward and underneath the roller 346 and forward underneath the 95 roller 345 and then up and passed over a stud 351, carried by the plate 335, and then down and wound around a receiving roll 352 (Figs. 7 and 11) rotatably mounted on a stud 353 carried by the plate 335. 100

The ribbon for inking the type wheels is illustrated in Fig. 7 by a line 355. The mechanism for carrying and feeding said ribbon is not a part of this invention, therefore it is not illustrated in the drawings 105 which accompany this specification, nor is it described herein, as any well known ribbon mechanism may be used for this purpose. From the above description it will be readily seen that the record strip passes 110

between the resilient roller 345, over the ribbon 355, and type wheels 317.

The means for engaging the resilient roller 345 with the type wheels 317 will now 5 be described. It comprises, an arm 356 (Fig. 5) fast upon the shaft 337. Projecting laterally from the arm 356 is a stud 357 (Figs. 2, 5 and 19) engaged by the upper bifurcated end 358 of a pitman 359 which is also 10 bifurcated at its lower end to surround the shaft 34. The pitman 359 is provided with an anti-friction roller 360 (Fig. 19) which 15 engages a cam race 361 in a disk 362. The disk 362 is fast upon the shaft 34 as is illustrated in Fig. 2. Pivotaly mounted to the pitman 359 at point 363 is an arm 364 (Figs. 1, 2 and 19) formed with a shoulder 365 (Fig. 19) to engage the stud 357 carried by the arm 356, and which is held by a spring 20 366 strained between the arm 364 and a stud 367 carried by the pitman 359. The configuration of the cam race 361 in the disk 362, is such that, at the proper time, and 25 after the actuators and type wheels have been differentially positioned, the pitman 359 will be moved downward and will cause the arm 356 through the arm 364 and stud 357, to be rocked in a clockwise direction. The arm 356 being fast to the shaft 337 will 30 cause said shaft to receive said clockwise rotation, and also the plate 335, it being remembered that said plate is also fast upon the shaft 337. This movement is sufficient to cause the resilient roller 344 to engage the 35 type wheels 324 so that the amount which has been set thereon will be printed upon the record strip. The ribbon 355 is of sufficient width to also cover the clerk's initial, 40 transaction type wheels and the consecutive number counters, so that the clerk's initial, transaction and consecutive number will also be printed upon said record strip as is illustrated in Fig. 1. The cabinet 25 is provided with an opening 368 (Figs. 7 and 23) so 45 that several of the record prints which are on the record strip are visible to the operator at one time. The record strip is protected by a glass 369 (Figs. 7 and 23).

The mechanism for feeding the record 50 strip will now be described and comprises, a ratchet 370 (Fig. 11) that is fast upon the receiving roll 352. Loose upon the stud 353 is an arm 371 that is yoked at 372 which carries an arm 373 (Fig. 19) that has a pin 374 55 projecting laterally therefrom. Pivotaly mounted upon the arm 371 is a spring pressed pawl 375 (Fig. 11) which engages the teeth of the ratchet 370. The pin 374 is 60 engaged by a hook 376 (Figs. 5 and 19) pivotaly mounted to an L-shaped arm 377 that is mounted stationary upon the shaft 337 and a horizontal shaft 378 mounted in bearings in the vertical walls 26 and 27. At the 65 proper time during the revolution of the disk 362, and after the printing has taken

place on the record strip, the pitman 359 is moved upward by means of the cam race 361 and roller 360 that is fast to the pitman 359. This upward movement of the pitman 359 will, through its engagement with the pin 357 cause the arm 356 the shaft 337 and plate 335 to be rocked in a counter clockwise direction, it being remembered that the arm 357 and plate 335 are fast upon the shaft 337. While the plate 335 is being thus 70 rocked the hook 376 being mounted upon the stationary L-shaped arm 377 will cause the arm 371 (Figs. 11 and 19), through the engagement of said hook with the pin 374 carried by the arm 373 that is integral with the 80 arm 371, to be rocked in a clockwise direction whereby the pawl 375 carried by the arm 371 will also be moved in a clockwise direction and turn the ratchet 370 a distance of one tooth. The ratchet 370 being fast 85 to the receiving rolls will cause said rolls to be wound up a sufficient amount to space the printing on the record strip for the print for the next item. The ratchet 370 and receiving roll 352 are prevented from 90 any retrograde movement by a spring pressed pawl 379 (Fig. 11) that engages the teeth of the ratchet 370.

When it is necessary to replace the supply roll 339 the operator moves the lever 95 364 (Fig. 19) clockwise thereby disengaging the shoulder 365, thereon from the pin 357. This movement of the lever 364 will cause the hook 376, by a link 380 (Figs. 1, 2 and 19) which is pivotaly fastened to the lever 100 364 and hook 376, to be disengaged from the pin 374 carried by the arm 373. After the hook 376 and lever 364 have been disengaged as above described, the plate 335 and arm 356 may be manually rotated in a 105 counter clockwise direction (Figs. 7 and 19) until the notch 381, formed in the lever 364, can be hooked over the pin 357 thereby holding the plate 335 and arm 356 in this outward disengaged position. While these 110 plates and arms are disengaged the pitman 359 is held in its normal position by means of a stud 381 carried by the side frame 26, which engages a slot 382 formed in said pitman.

A portion of the record strip, as printed by the machine herein, is illustrated in Fig. 24. The top line of printing represents, beginning at the left hand side, first the consecutive number, second the character of 120 transaction, which was a "paid out" transaction in this case, the next letter "N" represents the clerk which made the transaction, and the figures at the extreme right represent the amount of the "paid out" 125 transaction. The second line of printing beginning at the left represents first the consecutive number, second the character of transaction, which in this case was a "received on account" transaction, the next let- 130

ter "D" represents the clerk who made the transaction and the last figures represent the amount of said transaction. The next three lines of printing represent one transaction which in this case was a "cash" transaction represented by the star, the clerk was represented by the character "E" and the amounts represented as illustrated. It will be seen that the consecutive number for the last three above mentioned lines is the same, this being due to the fact that the consecutive number is only advanced one for each complete transaction of the machine, which constitutes the issuing of a slip and which will be hereinafter described. The next four lines represent a "charge" transaction made by clerk "A" the amount being shown for each separate item that was bought. The last line of printing on the portion of the strip as illustrated in Fig. 24 represents a total print of the above transaction as recorded. It will be also noticed that this amount is not a total of all the detail print above, as it will be remembered that the totalizer is only engaged and accumulated upon for a "cash" or "received on account" transaction, while for a paid out or charge transaction the totalizer is not engaged therefore and nothing can be accumulated thereon.

The interlocking mechanism.

As previously stated the machine herein is provided with a mechanism which compels the operator to first move or position the clerks initial lever before either the transaction or any of the amount levers can be manipulated to position the actuators. This mechanism comprises, the horizontal shaft 309 (Figs. 1, 5, 7 and 11) that is rotatably mounted in bearings in the vertical walls 26 and 27. Mounted fast upon the shaft 309 and projecting forward therefrom, are two arms 383 (Figs. 1 and 11) and 45 384 (Fig. 7). The arms 383 and 384 are so spaced upon the shaft 309 that a horizontal rod 385 (Figs. 1, 7 and 11), carried by said arms, engages a projection 386 that is integral with each of the amount actuators 59 50 and the transaction actuator 67 (Fig. 11). The rod 385 also engages a portion 387 of the clerk's initial actuator 71 (Fig. 13) that is integral with the clerks initial lever 74. By referring to Figs. 7 and 11 it will be seen that the transaction lever 70 and the amount lever 66 cannot be moved upward, since the rod 385, above described, is directly in front of the projections 386 which are integral with each of said levers. By referring to Fig. 13 it will also be seen that the projection 387 of the actuators, integral with the clerk's initial lever 74, is so formed that when the said lever is moved upward the rod 385 will be cammed downward a sufficient distance to position it be-

low the projections 386 on the amount actuators 59 and transaction actuator 67, thereby allowing said actuators to be positioned and to set up the transaction and amount as desired. This downward movement of the rod 385 causes the arms 383 and 384 to be rocked clockwise, therefore the shaft 309 will also be rocked clockwise, as it will be remembered the arms 383 and 384 are fast upon said shaft. The clockwise oscillation of the shaft 309 causes an arm 388 (Fig. 5) which is provided with two V-shaped notches 389 and 390, to also be moved in a clockwise direction, said arm being fast to said shaft. This movement will cause a spring pressed pawl 391, loose upon a horizontal shaft 392, to be disengaged from the V-shaped notch 389 (shown in Fig. 5) and to be engaged in the notch 390. After the pawl 391 has been engaged with the V-shaped notch 390 it will prevent any retrograde movement of the arms 383, 384 and 388 thereby causing the rod 385 (Figs. 7 and 11) to remain away from the projection 386 upon the amount actuators 59 and the transaction actuator 67 so that any of the levers may be set at leisure. The interlocking mechanism, above described, is restored to its home or normal position by means of a projection 393 (Fig. 5) that is integral with the link 329 previously described, and which it will be remembered is given an upward movement to feed the consecutive numbers. During this upward movement of the link 329 the projection 393 100 engages a pin 394, carried by the arm 388 and causes said arm to be rocked in a counter clockwise direction, whereby the pawl 391 will be disengaged from the notch 390 and will engage the notch 389 of the arm 105 388. This movement will cause the arms 383 and 384 to be rocked likewise, it being remembered that all three arms are fastened upon the shaft 309. The rocking of the arms 383 and 384 will position the rod 385 110 in front of the projections 386 that are integral with the amount actuators 59 and the transaction actuator 67, this being the normal and home position of said rod. As stated before, the machine herein is so 115 designed that the operator is compelled to print the total from the transaction totalizer and issue a slip for every transaction recorded on said machine. This is accomplished by a mechanism which locks the 120 clerk's initial lever, automatically, and is held locked until the operator has issued a slip. This mechanism will now be described. It comprises a bail 395 (Figs. 2 and 11) carried by an arm 396 and a lever 397 which 125 are loosely mounted upon the shaft 93. The bail 395, arm 396 and lever 397 are held in their normal position by a pawl 398 (Figs. 2 and 11) that is loosely mounted upon the shaft 225. The pawl 398 is held in engage- 130

ment with a V-shaped notch 399 in a portion 400, integral with the lever 397, by a coil spring 401 that is strained between said pawl and said lever.

- 5 At the proper time during the revolution of the cam shaft 38, a stud 402 (Figs. 2 and 11), carried by the disk 121, engages the portion 400 of the lever 397 and rocks the lever clockwise, thereby causing the pawl 398 to 10 be cammed out of the notch 399 and to engage another V-shaped notch 403, which is also in the portion 400 integral with the lever 397. This movement of the lever 397 is sufficient to cause the bail 395, integral 15 therewith, to engage the upper part of the portion 123 integral with the pawl 87, thereby preventing the nose 88, integral with said pawl, from being removed from the notch 89 in the actuator 71 (Fig. 13) that is integral 20 with the clerk's initial lever.

Pivotedly mounted to a portion 404 (Fig. 11), integral with the lever 397, is the upper end of a pitman 405 which is bifurcated at 406 to surround the shaft 259, as is illustrated in Figs. 1 and 11. When the lever 397 is rocked in a clockwise direction, as above described, the pitman 405 will be moved downward, thereby causing an anti-friction roller 407 carried by said pitman, to 25 be positioned very close to the periphery of a cam 408 (Figs. 1 and 11) that is fast upon the shaft 259. It will be remembered that after the lever 397 has been rocked clockwise and causes the pawl 398 to engage the notch 30 403 of said lever, thereby retaining it in this position, it also retains the roller 407 in the position just described. At the proper time, and by means which will be hereinafter described, the shaft 259 is rocked in a clockwise 35 direction. This clockwise movement of the shaft 259 causes the cam 408, fast thereto, to also be rocked likewise and engage the roller 407 of the pitman 405 and cause said pitman to be moved upward. The upward movement 40 of this pitman causes the lever 397 to be rocked in a counter clockwise direction, whereby the pawl 398 is disengaged from the notch 403 and again engaged in the notch 399 which is the normal position. This 45 movement of the lever 397 is sufficient to disengage the bail 395 from the projection 123 of the pawl 87, thereby unlocking said pawl for a subsequent operation of the machine.

55 *Slip printer.*

As before stated, the machine herein is provided with a printing mechanism that is adapted to print the "date," "character of 60 transaction," "clerk's initial," "the amount of transaction" and the consecutive number on a "sales slip." Said mechanism will now be described. It comprises, one "month" type wheel 410 (Figs. 1 and 11) and two "daily" 65 type wheels 411 (Fig. 1). The month wheel

410 is provided with type on its periphery, of the numerals one to twelve, inclusive, said type representing the months of the year.

The "daily" type wheels 411 are also provided with type, on their peripheries which 70 represent the days of the month. Secured to the side of each of the type wheels 410 and 411 is a disk 412 (Fig. 11). These type wheels are rotatably mounted upon the shaft 256. Mounted loosely upon the shaft 262 are three 75 spring pressed pawls 413 (Figs. 1 and 11) that engage V-shaped notches 414, in the periphery of each of the disks 412, and serve to hold the type wheels 410 and 411 in perfect alinement for printing. These wheels 410 and 411 project through the cabinet at the front of the machine so that the type thereon are visible. To set up the date for printing, the operator simply turns each type wheel manually with the finger, pencil or any suitable element, 80 until the desired date type are positioned directly opposite the ink pad as illustrated in Fig. 11 and to be hereinafter described. Mounted loose upon the sleeve 255 (Fig. 1) 85 is a transaction type wheel 415 and a clerk's 90 initial type wheel 416.

Secured to the side of each of said type wheels is a pinion 417 and 418 (Fig. 1) respectively. These pinions 417 and 418 are arranged to mesh with the teeth 69 (Fig. 11) 95 and 73 (Fig. 13) respectively which, it will be remembered, are integral with the transaction actuator 67 and clerks initial actuator 73. The type wheels 410 and 411 are held in alinement for printing and are locked and 100 unlocked by pawls 419 (Figs. 1 and 11) loosely mounted on the shaft 262, said pawls are identical with the pawls 261 (Figs. 1 and 7) which, it will be remembered, coöperate with the amount counter wheels 254 (Figs. 105 1 and 7), and receive their positive movement, simultaneous, and by the same device as do pawls 261. When the transaction lever 70 and clerks initial lever 74 (Fig. 21) are positioned, as previously described, the type 110 wheels 415 and 416 coöperating therewith, will also be positioned for printing. The counter wheels 254 are provided with type 420 (Fig. 7) on their peripheries so that the amounts which have been accumulated upon 115 said counter wheels may be printed upon the sales slip. During the clockwise rotation of the sleeve 255 (Fig. 7^A) the type wheels 415 and 416 are rotated to zero as previously 120 described.

The device for inking the above described type wheels is best illustrated in Figs. 1, 7 and 15 and comprises, a pad 421 (Figs. 5, 7, 11 and 15), made of felt or any other material suitable for absorbing ink, carried by a 125 block 422 fastened to formed portions 423 (Fig. 5) and 424 (Figs. 7 and 15) that are integral with parallel links 425 (Figs. 1 and 5) and 426 (Figs. 1, 7 and 15) respectively. The links 425 and 426 are pivotally fastened 130

- to arms 427 (Figs. 1 and 5) and 428 (Figs. 1, 7 and 15) respectively, which are rotatably mounted upon the shaft 262. The lower end of each of the links 425 and 426 is provided 5 with a slot 429 (Fig. 5) and 430 (Figs. 7 and 15), respectively, to receive pins 431 and 432 carried by arms 433 (Figs. 1 and 5) and 434 (Figs. 1, 7 and 15), respectively, fast upon a shaft 435 which is rotatably mounted in 10 bearings in the plates 257 and 258. Also fast upon the shaft 435 is an arm 436 to which is pivotally mounted the upper end of a link 437 (Figs. 1, 7, 15, and 16) provided with a slot 438 (Fig. 16) to receive the 15 shaft 259. The extreme lower end of the link 437 is provided with an anti-friction roller 439 which engages a cam race 440, and fits therewithin, that is formed in a plate 441 (Figs. 1, 15 and 16), said plate being 20 mounted upon the shaft 259 and held stationary by means of a pin 442 (Figs. 15 and 16) that is driven through said plate and into the vertical wall 27 as said plate lies adjacent said wall.
- 25 When the plates 257 and 258 (Figs. 5 and 7) are manually rotated in a clockwise direction, as hereinafter to be described the shaft 435, (it being remembered that said shaft is carried by said plate,) will be moved 30 forward and downward, or in other words rocked clockwise around the shaft 259. While the shaft 435 is being moved as above described, it will be first oscillated in a counter-clockwise direction and then in a clockwise direction. These oscillations are caused 35 by the cam race 440, in the plate 441, which engages the anti-friction roller 439 carried by the link 437, said link being pivotally mounted to the arm 436 fast upon the shaft 40 435. The first or counter-clockwise oscillation of this shaft 435 will cause the arms 433 and 434, fast thereto to also be oscillated in a counter-clockwise direction whereby the arms 427 (Fig. 5) and 428 (Figs. 7 and 15) 45 through the links 425 and 426, will also be rotated counter-clockwise around the shaft 262. As the arms 433 and 434 are being oscillated counter-clockwise the pins 431 and 432, carried by said arms, slide in the slots 50 429 and 430, of the links 425 and 426, respectively, and cause said links to rock counter-clockwise on their pivots on the arms 427 and 428 respectively, whereby the ink pad 421 is brought into contact with the type 55 wheels 410 and 411 and also the counter wheels 254 and inks said wheels for printing. Immediately after the ink pad 421 has inked the type as above described the link 437 (Fig. 16) is moved downward, by the engagement of the roller 439 thereon with the cam slot 440, thereby causing the arm 436 and shaft 435 to be oscillated in a clockwise direction. This clockwise oscillation of the 60 shaft 435 will oscillate the arms 433 and 434 likewise whereby the links 425 and 426 will be pulled downward moving the arms 427 and 428 in a clockwise direction, which will move the ink pad 421 a distance which is sufficient to allow the type wheels to print upon the sales slip, hereinafter described. 70
- Means whereby the date type wheels 410 and 411, the transaction type wheel 415, the clerk's initial type wheel 416, and the type upon the amount wheels 254 are brought into contact with the sales slip will now 75 be described and comprises a lever 443 (Figs. 1, 5 and 23) that is fast upon the shaft 256. Also fast upon the shaft 256 is a lever 444 to which is pivotally mounted the upper end of a link 445 (Figs. 1 and 5), 80 the lower end of which is pivotally mounted on another lever 446 that is rotatably mounted upon the shaft 259. Integral with the lever 446 is an arm 447 (Figs. 1 and 5) that has fastened thereto a coil spring 448 85 the other end of which is fast upon a stud 449 carried by the vertical wall 26. Integral with the lever 446 and arm 447 is a projection 450 (Fig. 5) that is held against a stud 451, carried by the plate 257, by the action 90 of the spring 448 above described. This also serves to hold the lever 443 in its normal position as shown in Fig. 5.
- In order to engage the type wheels and type upon the counter wheels above 95 described, with the sales slip, which will be hereinafter described, so that a record may be printed thereon, the operator takes hold of the lever 443 and moves said lever downward. This movement causes the shaft 256 100 and plates 257 and 258 to be rocked in a clockwise direction around the shaft 259, it being understood that the spring 448 (Fig. 5) is strong enough to hold the lever 443 from turning the shaft 256 so that the plates 105 257 and 258 can be rocked as just described. Integral with the lever 444 is a hook 452 (Fig. 5). Fast upon the shaft 256 is another hook 453 (Figs. 1 and 7). When the lever 443 is in a horizontal position, as it is being 110 moved downward, the hooks 452 and 453 will engage two rollers 454 (Figs. 1, 5, 7 and 23), which are carried by the vertical walls 26 and 27 as illustrated in Fig. 1. As the hooks 452 and 453 engage the rollers 454 115 the operator exerts an extra downward pressure upon the lever 443 which, so to speak, "breaks" said lever from the arms 257 and 258, and causes the type wheels above described, to be brought firmly against 120 the sales slip which lies, as is to be herein-after described, directly above a resilient platen 456 (Fig. 7) mounted in a block 457 carried by a front wall 458 fast upon the horizontal base 28. This causes the date, 125 character of transaction, clerk's initial and the amount of said transaction to be printed upon said sales slip. In "breaking" the lever 443 as mentioned above, it simply causes a slight extra oscillation of said lever 130

which causes the hooks 452 and 453 (Figs. 5 and 7) to firmly grip the rollers 454. It also causes the lever 444 to be oscillated in a clockwise direction which raises the link 445 and oscillates the lever 446 in a clockwise direction, which causes the portion 450, integral with the lever 446, to be moved away from the pin 451, which, it will be remembered, is carried by the plate 257, thereby causing an extra tension to be put upon the spring 448. After the lever 443 has been pressed as far as possible, it is released and the spring 448 causes the lever 446 and arm 447 to be rotated counter-clockwise until the portion 450, integral therewith, again engages the pin 451 which will cause the plates 257 and 258 and the counter and printer above described, to be returned to their normal position. This movement will also rotate the shaft 259 counter-clockwise which will return all the cams and members fast thereto to their normal positions.

As before stated the slip printer lever 443 is inoperative during the operation of the crank handle 40 (Fig. 1). This is accomplished by means of a lever 460 (Figs. 2, 3 and 4), having integral therewith a projection 461 that lies in the same plane with the disk 45 (Figs. 2, 3 and 4), and which is arranged to engage a square notch 462 in the disk 45, when said disk is in its home position. Integral with the lever 460 is an arm 463 (Figs. 3 and 4) which carries an anti-friction roller 464, that is engaged by the periphery of a segmental plate 465 fast upon the shaft 259. If the crank handle 40 (Fig. 1) is in its home position the disk 45 will also be in its home position as is illustrated in Figs. 3 and 4, so that, when the shaft 259 is rotated in a counter-clockwise direction (Fig. 3) by the lever 443 and the segmental plate 465 is rotated likewise and engages the roller 464 and causes the lever 460 to be rocked counter-clockwise, the portion 461, will enter the notch 462 in the disk 45 and prevent operation of the handle 40 while the lever 443 is being operated. Should the crank handle 40 not be way home, the disk 45 will then be in such a position that the notch 462 will not be in front of the portion 461, as illustrated in Fig. 4, therefore the portion 461 will strike the true periphery of the disk 45 so that the lever 460 cannot be rotated. This will lock the shaft 259 in its normal position, by means of the roller 464 which, it will be remembered, lies against the periphery of the segmental plate 465 fast upon the shaft 259. As stated at the beginning of the specification, the crank handle 40 must be operated and be in its home position before the slip printer lever 443 can be operated.

65 The mechanism for releasing the slip

printer lever 443 will now be described. It comprises, the pin 57 (Figs. 2, 3 and 4), which it will be remembered is carried by the disk 45, and which engages a lever 466 (Figs. 2 and 3) and rocks said lever clockwise. 70 The lever 466 is held in its normal position, as illustrated in Fig. 3, by means of a spring pressed pawl 467 that engages a V-shaped notch 468 formed in the lever 466. The pawl 467 is rotatably mounted upon a stud 469 (Figs. 2 and 3) carried by the vertical wall 27. During the first part of the revolution of the crank handle 40, and disk 45, the pin 57 engages the lever 466 and rocks said lever clockwise thereby causing the 80 pawl 467 to be disengaged from the notch 468 and to engage another V-shaped notch 470, formed in the lever 466. Integral with said lever is a downwardly projecting arm 471 which has pivotally fastened thereto a 85 link 472 (Figs. 2, 3 and 17). The link 472 is provided with a laterally projecting pin 473 that engages an elongated slot 474 formed in the upper portion of a bell crank 475 (Fig. 3) which is loosely mounted upon 90 a stud 476 carried by the vertical wall 26. The rearwardly projecting portion of the bell crank 475 carries a pin 478 that engages a portion 479 integral with an arm 480 also loosely mounted upon the stud 476. 95 The portion 479 of the arm 480 is held in engagement with the pin 478 by means of a spring 481 that is strained between said arm and a stud 482 carried by the vertical wall 26 as illustrated in Fig. 2. When the lever 100 466 is rocked clockwise, as above described, the arm 471, integral therewith, will also be rocked in a clockwise direction whereby the bell crank 475, through the engagement of the pin 478 and slot 474, will be rotated in 105 a counter-clockwise direction, whereby the pin 478 will rock the arm 480 in a counter-clockwise direction so that said arm will be positioned below a square stud 483, carried by the segmental plate 465, so that said plate 110 and the shaft 259 may be rotated.

From the above description and referring to Fig. 3, it will be readily seen that if the crank handle 40 (Fig. 1) has not been operated the pin 57 carried by the disk 45 will 115 not be moved, therefore the lever 466 will remain in the position shown in Fig. 3. The bell crank 475 and the arm 480 will also remain in their home positions so that should the operator attempt to operate the 120 slip printer lever 443 the square stud 483 would immediately contact with the end of the arm 480, therefore the said slip printer lever 443 is prevented from being operated. After the crank handle has been operated, and the mechanism just described has been 125 displaced, the pawl 467 is engaged in the notch 470. The means for restoring this mechanism to its normal position will now be described. It comprises a pin 484 (Fig. 130

3) projecting laterally from the link 472 that is engaged by a downwardly projecting arm 485 (Figs. 1 and 3) that is fast upon the shaft 259. When said shaft is rocked, 5 by the operation of the slip printer lever 443, in a counter-clockwise direction (Fig. 3), the arm 485 engages the pin 484 and causes the link 472 to be moved rearward a sufficient distance to rock the arm 471, integral 10 with the lever 466, in a counter-clockwise direction so that the pawl 467 will be disengaged from the notch 470 and again engage the notch 468, which is the normal and home position of the lever 466 as illustrated in 15 Fig. 3.

Included in the slip printer mechanism is a cylinder 490 (Figs. 1, 2, 7, 11 and 21), said cylinder having both ends inclosed by caps 491 (Figs. 1 and 11) and 492 (Figs. 1 and 2) 20 fast to the cylinder 490. The cap 491 is provided with a hub like projection 493 (Figs. 1, 2, 5 and 11) which fits within a bearing in a flanged hub 494 (Figs. 1 and 2) that is mounted fast to the vertical wall 26. 25 The cap 492 is provided with a hole 495 (Fig. 7) into which projects and fits a stud 496 (Figs. 1 and 2). Mounted upon the outside of the cylinder 490 and between the caps 491 and 492 is an electro 497 (Fig. 7) 30 for the purpose of printing upon the sales slip. This electro is inked for printing by means of a roller 498, made of felt or any other suitable material for absorbing ink (Figs. 2, 7 and 11), which is mounted fast 35 upon a sleeve 499 rotatably mounted upon a shaft 500 carried by parallel arms 501 rotatably mounted upon a shaft 502. The ink roller 498 is normally held in engagement with the electro 497 by means of two 40 springs 503 (Figs. 2 and 5) strained between each of the arms 501 and pins 504 carried by the vertical walls 26 and 27, as illustrated in Fig. 2. The shaft 500 is long enough and is so mounted in the arms 501 that it, 45 with the ink roller 498, may be easily removed from the machine in order to re-ink said roller when it is necessary.

Means whereby the impression is taken from the electro 497 onto the slip paper will 50 now be described. It comprises two parallel arms 505 (Figs. 2, 7, 11 and 21) fast upon the shaft 502. Carried by the arms 505 is a shaft 506 upon which is rotatably mounted a sleeve 507 having fastened thereto a 55 silent roller 508. Also fast to the shaft 502 is an arm 509 (Figs. 1, 2 and 21) that carries an anti-friction roller 510 held against the periphery of a segmental plate 511 by means of a spring 512 strained between the 60 arm 509 and a stud 513 carried by the vertical wall 26. The segmental plate 511 is fast upon the shaft 259, and its periphery is so formed that when the shaft 259 is rocked in a clockwise direction (Fig. 21) the 65 arm 509, through the engagement of the

plate 511 with the roller 510, will be rocked in a counter-clockwise direction which causes the shaft 502 and the arms 505, which, it will be remembered, are all fast to the shaft 502, to be rocked counter-clockwise. This movement is sufficient to cause the roller 508 to contact with the electro 497, as the electro is being revolved with the cylinder and as will be hereinafter described. The engagement of the roller 508 with the electro 497 70 also helps to feed the sales slip paper through the machine.

The mechanism for revolving the cylinder and electro thereon, as is illustrated in Figs. 2 and 7, comprises, a pinion 514 fast upon a 80 sleeve 515 (Fig. 2) loosely mounted upon the stud 496. Secured to the other end of the sleeve 515 is a snail cam 516 (Figs. 2 and 7) having a shoulder 517 (Fig. 7) that engages a spring pressed pawl 518 pivotally 85 mounted upon the cylinder cap 492. Meshing with the pinion 514 are the teeth of a segment 519 (Fig. 7) that is integral with the plate 258. When the plate 258 is rocked clockwise (Fig. 7), as previously described, 90 the segment 519 will be rocked likewise thereby causing the pinion 514 to be rocked in a counter-clockwise direction. This pinion 514 being fast to the snail cam 516 will cause said cam to receive said counter-clockwise rotation, which causes the cylinder 490, 95 through the engagement of the shoulder 517 of said cam with the pawl 518, to be revolved in a counter-clockwise direction. The cylinder 490 is kept from any excessive 100 overthrow movement by means of a pin 520 carried by the cylinder cap 492, that strikes against a plate 521 which is securely fastened to the segment 519 as illustrated in Fig. 7. When the plate 258 is rocked counter-clockwise (Fig. 7) the segment 519 will 105 be rocked likewise, thereby causing the pinion 514 and snail cam 516 to be revolved in a clockwise direction a distance sufficient to cause the shoulder 517 of said cam to 110 again engage the pawl 518. In order to prevent the cylinder from being revolved clockwise with the said pinion and cam, the cylinder cap 492 is provided with a stud 522 115 (Figs. 1 and 7) that is engaged by a spring pressed pawl 523 that is rotatably mounted on the shaft 259 thereby preventing any retrograde movement of the cylinder.

Mounted inside the cylinder 490 is a consecutive-number counter, which is of the 120 usual step by step type; therefore but a brief description of said counter will be given herein. A cylinder carrying a consecutive numbering device of this type is fully illustrated and described in Letters 125 Patent of the United States, No. 497,861, granted to Thomas Carney on May 23, 1893. This consecutive number counter comprises, four counter wheels 524 (Figs. 1 and 7) which are rotatably mounted upon a sleeve 130

525 that is loose upon a shaft 526 carried by the cylinder caps 491 and 492. This consecutive number counter is advanced one step at each revolution of the cylinder 490 by means 5 of a differentially tined pawl (not shown) carried by a frame 527 (shown partly in Fig. 1 and partly in Fig. 11). This frame carries an anti-friction roller 528 (Figs. 1 and 11) which engages a cam race 529 10 formed in a disk 530 (Fig. 5) that is integral with the flanged hub 494 (Figs. 1, 2 and 5). The hub 494 is held stationary by means of three pins 531 (Fig. 5) that are driven through the flange of the hub 494 and 15 the vertical wall 26. When the cylinder 490 is given a counter-clockwise revolution, as previously described, the frame 527, through the engagement of the roller 528 with the cam race 529, will be rocked in a counter-clockwise direction. The rocking of the frame 527 causes the differentially tined pawl (not shown) which engages a ratchet 20 5341 (Fig. 1) carried by each of the counter wheels 524, to move said ratchet and counter wheel one step. The counter wheels 524 project through an opening 532 in the cylinder 490 so that when said cylinder is revolved the type on the counter wheels 524 will engage the slip paper and cause the consecutive 25 30 number to be printed thereon.

The supply roll for the sales slip is not shown in the drawings which accompany this specification but is carried on the side of the machine and is arranged to be fed 35 in through the back of the cabinet 25, and through two paper guides 533 (Figs. 2, 5, 7 and 11) carried by two parallel brackets 534 (Figs. 2, 5 and 7), mounted upon the shaft 502 and a shaft 535 that is carried 40 by the vertical walls 26 and 27. There are two strips of paper that are fed from the same supply roll, the upper strip 536 (Fig. 17) is coated on its underneath side with any suitable material for duplicating, such 45 as carbon, the other strip 5361 is fed at the same time and lies directly beneath the strip 536, as illustrated in Fig. 17. As the strips 536 and 5361 come through the forward end 50 of the front paper chute 533 they go between a plate 537 (Figs. 5, 7 and 11) and a horizontal portion of the cabinet 25, and over parallel disks 538 which are mounted fast upon a sleeve 539 rotatably mounted upon a shaft 540 which is rotatably mounted 55 in bearings in the vertical walls 26 and 27. The disks 538 are each provided with a number of pins 541 (Figs. 7, 9, 10 and 11) mounted upon the periphery of said disk, and which engage holes 542 (Fig. 17) near 60 the edges of the sales slip paper.

The mechanism for revolving the disks 538 so that the slips may be fed from the machine will now be described. It comprises a segment 543 (Fig. 7) integral with 65 the plate 258, and having teeth which mesh

with the teeth of a rack 544 (Figs. 7 and 17) slidably mounted upon a stud 545, carried by the vertical wall 27, and a stud 546, carried by the rack 544 which engages a slot 547 formed in a plate 548 that lies 70 adjacent the said rack 544. The plate 548 is slidably mounted upon the stud 545 and another stud 5451, carried by the vertical wall 27, and is provided with teeth 549 (Fig. 7) that mesh with a pinion 550 rotatably mounted upon a stud 551, which is carried by the vertical wall 27. Secured to the side of the pinion 550 is a larger pinion 552 (Figs. 7 and 17) that meshes with a pinion 553 (Figs. 7 and 10) fast upon a hub 554 80 which has fastened to its other end a snail cam 555 that engages a spring pressed pawl 556 pivotally mounted upon a stud 557 carried by the disk 538, as shown in Figs. 7 and 10. When the plate 258 is rocked in a clockwise direction (Fig. 7), as previously described, the segment 543 will be rocked likewise thereby causing the rack 544 to be moved rearward until the stud 546 engages the rear end of the slot 547, 85 then the plate 548 will be carried along with the rack 544. This movement of the plate 548 will rotate the pinions 550 and 552 counter-clockwise causing a clockwise rotation of the pinion 543 and the snail cam 555. This clockwise rotation of the cam 555 causes the disk 538, through the engagement of said cam with the spring pressed pawl 556, to be revolved in a clockwise direction whereby the slip, through the 100 engagement of the pins 541 with the holes 542, will be fed forward so that it may be torn off by the operator. The adjustment for the feeding of the slip, that is, for the length of the slip, is made by a plate 559 105 pivotally mounted upon a stud 560 that is carried by the plate 548. The periphery of the plate 559 is eccentric with the center of the stud 560 so that should a longer or shorter slip be desired the plate may be 110 oscillated upon the stud 560 either in a clockwise or counter-clockwise direction so that when the stud 546 travels rearward it will engage the eccentric periphery of the plate 559 instead of the end of the slot 547 thereby causing the plate 548 to travel either a shorter or greater distance. The plate 559 is locked in any position in which it is set by means of a screw 561 that enters a slot 115 in the plate 559 and screws into the plate 548. When the plate 258 and segment 543 are returned to their normal position the rack 544 and plate 548 will be moved forward thereby causing a clockwise revolution of the pinions 550 and 552, which in 120 turn causes the pinion 553 and snail cam 555 to be rotated in a counter-clockwise direction. The disk 538 will not be revolved counter-clockwise with pinion 553 and the snail cam 559 due to the fact that a spring 125

pressed pawl 562 (Fig. 11) engages the pin 557 carried by the disk 538 so that said disk and the other disk 538 shown in Fig. 7 cannot be moved counter-clockwise. 5 The pawl 562 is pivotally mounted upon a shaft 563 (Figs. 7 and 11) that is carried by the vertical walls 26 and 27. The feeding mechanism above described is released simultaneous with the mechanism that releases the slip printer lever 443 by means of the link 472 (Figs. 3 and 17) that is pivotally mounted to an arm 565 that is fast upon the shaft 563. Also fast upon the shaft 563 is an arm 566 (Fig. 7), the 15 end of which lies directly behind the stud 557 so that the disks 538 are normally locked in this position by means of said arm 566 and the pawl 562 previously described. When the link 472 is moved forward, as 20 previously described, the arm 565 and the shaft 563 will be rotated in a counter-clockwise direction (Fig. 3) which causes the arm 566 to be moved in a clockwise direction (Fig. 7) a distance sufficient to position said 25 arm below the stud 557 so that when the slip printer lever 443 is operated, as previously described, the disk 538 will be allowed to revolve in a clockwise direction so that the slips will be fed from the machine. 30

The slip itself is illustrated in Fig. 18. This figure shows a sample of the original. The printing across the top represents, beginning at the left, the date "10-27," the next 35 "Ch" represents a charge account, "A" the clerk making said transaction, "\$24.40" represents the total amount of said transaction. The next three lines is printed by the electro 497 which, it will be remembered is carried by the cylinder 490. The words "clerk," "sold to," "address" and all the lines and printing matter at the bottom of the slip are also printed by the same electro which prints the name of the merchant above. The 40 figures "2164" at the bottom and right side represent the consecutive number as printed by the consecutive number counter, which, it will be remembered, is carried by the cylinder. The writing illustrated on the sample 45 slip as shown in Fig. 18 is done by the clerk operating the machine. As it will be remembered the machine herein is provided with an autographic feature which will be hereinafter described. The autographic 50 feature above mentioned simply comprises an opening 570 (Fig. 17) that is made in the horizontal portion of the cabinet 25 so that the clerk or operator of the machine may write upon the sales slip before it is 55 issued using the plate 537 shown in Fig. 7 as the table.

Drawer release.

The mechanism for releasing the drawer 60 so that it can be opened is controlled by the

slip printer lever, as previously stated, and comprises the segmental plate 465 (Fig. 3), the lever 460, the arm 463 integral therewith, and a pin 571 projecting laterally from the arm 463, that engages an arm 572 (Figs. 70 1, 2 and 3) rotatably mounted upon the stud 49. When the slip printer lever 443 is operated, as previously described, the shaft 259 and the segmental plate 465 are rotated in a counter-clockwise direction (Fig. 3) a sufficient 75 distance to cause the higher periphery of the said plate which, it will be remembered, engages an anti-friction roller 464 carried by the arm 463, to move the arm 463 in a counter-clockwise direction. This 80 movement of the arm 463 causes the arm 572, through the engagement of the pin 571 with the said arm, to be rocked in a counter-clockwise direction which causes an arm 573 (Fig. 3) to be rocked clockwise through the 85 engagement of a pin and slot in the arms 572 and 573. The arm 573 is fast upon a shaft 574 (Figs. 1 and 3) rotatably mounted in a U-shaped bracket 575 carried by the cabinet 29. Also fast upon the shaft 574 is a hook 90 576 that engages an L-shaped bracket 577 fastened to the rear end of the drawer 30, as illustrated in Figs. 1 and 3. The hook 576 is held in its normal position, as illustrated in Fig. 3, by means of a torsion spring 95 578 that is strained between the bracket 575 and the hook 576. The clockwise rotation of the arm 573 causes the shaft 574 and the hook 576 to also be rotated likewise, which is sufficient to cause the end of the hook to 100 be disengaged from the bracket 577, thereby allowing the drawer to be opened. This mechanism cannot be operated while the crank handle is being operated, as it will be remembered the slip printer lever is locked 105 during the operation of the said crank handle. When the slip printer lever 443 is returned to its home position the segmental plate 465 will be rotated in a clockwise direction (Fig. 3) thereby allowing the arms 110 463, 572 and 573 to be returned to their normal positions by the action of the spring 578 upon the hook 576, it being remembered that the hook 576 is fast upon the same shaft that the arm 573 is fast. 115

Total taking.

The mechanism for taking totals and sub-totals of the amount upon the grand totalizer will now be described. It comprises a 120 lever 580 (Figs. 1, 2, 7 and 23) pivotally mounted upon the shaft 93. Integral with the lever 580 is a formed portion 581, having a spring 582 strained between said portion and a stud 5831 carried by the vertical wall 125 27. This spring holds the lever 580 in its normal position. To take a subtotal the operator pulls the lever 580 forward and downward which causes the portion 581 to be rotated in a clockwise direction so that it will 130

engage a portion 583 (Figs. 1 and 7), integral with a lever 584 fast upon the shaft 81, and cause said lever and shaft to be rotated in a counter-clockwise direction. This 5 counter-clockwise movement of the shaft 81 causes the arm 236 (Fig. 11) to be rotated counter-clockwise thereby causing the roller 237 carried by said arm to engage the lower portion of the cam slot 238 in the plate 205 10 whereby said plate, which, it will be remembered, carries the grand totalizer, to be rocked in a clockwise direction. This clockwise movement of the plate 205 is sufficient to cause the counter wheels 200 and 15 type 585, which is formed on the peripheries of said counter wheels, to engage the resilient roller 346 (Figs. 7 and 11), thereby causing the amount which has been accumulated upon said grand totalizer to be printed 20 upon the record strip. The lever 580 is then moved upward which causes the portion 581, integral therewith, to engage a formed portion 586, integral with the lever 584, and rock said lever in a clockwise direction which 25 also rocks the shaft 81 and the arm 236 in a clockwise direction, thereby causing plate 205 through the engagement of the roller 237 with the slot 238 to be moved downward to its normal position.

30 This operation does not turn the grand totalizer to zero therefore it is but a sub-total. In order to take a total the operator goes through identically the same operation and the mechanism performs exactly the 35 same function as taking a sub-total, but after the lever 580 has been returned to its normal position the operator inserts, through the side of the cabinet, a key (not shown) which engages a mortise 5861 in a hub 587 that is 40 integral with a disk 588 (Fig. 6) fast upon the shaft 203. The key is turned so that the shaft 203 will be revolved counter-clockwise (Figs. 7 and 8) so that the pawls (not shown) which are carried by each of the 45 counter wheels will be engaged by a notch 5881 and cause said wheels to be turned to zero. This is called a total taking operation for the reason that the next time the counter is engaged with the actuators a new amount 50 will be accumulated thereon, the old one having been cleared. During the taking of the sub-total and total the pitman 116 (Fig. 11) is moved downward, it being remembered that the said pitman is pivoted to the 55 lever 114 also fast upon the shaft 81. As the cam shaft 38 is not operated during a taking of a sub-total or a total there must be some clearance for the anti-friction roller 119 carried by said pitman, therefore a notch 60 1181 (Fig. 11) is provided in the cam race 120 in which the anti-friction roller 119 operates. After the total lever 580 has been started downward it is impossible to operate the crank handle 40. This is accomplished 65 by means of an arm 589 (Fig. 7) fast upon

the cam shaft 38. As the lever 580 is rotated clockwise a formed portion 590, integral therewith, rocks directly beneath the arm 589 thereby locking the cam shaft 38 from any oscillation and also locking the crank 70 handle 40.

Operation.

Let it be assumed that the machine herein above described is being used in a store that 75 handles groceries and meat. A Mr. "Richard Roe" who has a charge account at the store above mentioned, comes in and wishes to buy several different articles, such as bread, potatoes, eggs, flour, meat, etc. The 80 clerk that waits on Mr. Roe has for his initial the letter "A." After wrapping up Mr. Roe's articles, clerk "A" goes to the register and first moves the clerk's initial lever 74 (Fig. 23) up until the pointer 79 thereon is opposite the letter "A". Mr. Roe bought his goods on a charge account, therefore the 85 clerk will next move the transaction lever 70 upward until the pointer 79 thereon is opposite the word "charge." Let us say for instance that the first article that Mr. Roe bought was bread which amounted to 30¢; clerk "A" now operates the amount levers 66 upward until the pointers thereon indicate the amount 30¢. When the clerk's initial 90 lever 74 was moved upward, the lever, being integral with the clerk's initial actuator 71 (Fig. 13), caused the shaft 385 to be moved downward, thereby releasing it from in front of the projections 386 that are integral with 95 each of the amount actuators 59 and also the transaction actuator 67. This allows the operator to manipulate the transaction levers and any of the amount levers, as previously described. The setting of the levers just described causes the character of transaction, which was in this case charge, the clerk's initial, and the amount of this item to be set upon the type wheels 317, 320 and 322, which 100 are illustrated in Fig. 1. This also positions 105 the actuators, so that the clerk's initial, character of transaction, and amount of said transaction, will be set up ready for the transaction totalizer to come in engagement with said actuators. After the levers 66, 70 110 and 74 have been positioned to set up the amount, character of transaction and the clerk's initial, the crank handle 40 is moved slightly in the inoperative direction which causes the cam shaft 38 and disk 45 (Figs. 3 115 and 4), through the train of gears illustrated in Fig. 3, to be rocked slightly clockwise. This movement of the disk 45 allows the forked lever 47 to be rocked counter-clockwise by the coil spring 50, which disengages 120 the end 46 of said lever from the notch 48 in the disk 45 thereby allowing the crank handle to be turned in its operative direction. When the crank handle is given two revolutions in the operative direction, it causes the 125 130

cam shafts 38, through the train of gears (Fig. 3) to be revolved once in a counter-clockwise direction (Figs. 3 and 4) and in a clockwise direction (Figs. 5, 7, 11, 15, 19, 22, 25 and 23). At the very beginning of the cam shaft cycle the square stud 98 (Fig. 5) carried by the disk 99 is moved clockwise so that it will come directly beneath the arm 97 until the portion 100 of the disk 99 can get beneath the roller 101 carried by said arm. This causes the arm 92 to be held in the position shown in Fig. 7, so that the rod 91 (Figs. 7 and 11), will lie against the edges 94 of the pawls 80 thereby holding the noses 88 of said pawls in engagement with the V-shaped notches 84 of the amount actuators thereby alining said actuators and the type wheels. This also holds the rod 91 against the edges 94 of the pawls 87 that engage the clerk's initial actuators and the transaction actuator thereby locking said actuators from any movement, forward or retrograde. At the same time the actuators are locked, the pawls 261 (Figs. 7 and 15) that lock the counter wheels of the transaction totalizer are unlocked by means of the link 267, which is moved upward by the pin 279 carried by the lever 270 which is rocked clockwise by the pitman 274 through the roller 276 and cam race 277 of the disk 278. This causes the bell cranks 265 and 266 to be rocked clockwise which moves the rod 263 away from the portion 264 of the pawls 261 thereby allowing said pawls to be released from the pinions 260 on the counter wheels 254. Immediately after the transaction actuator, clerk's initial actuator and amount actuators have been locked by the alining pawls, as previously described, the plates 335 (Figs. 11 and 19) and 341 (Fig. 7) are rocked in a clockwise direction, so that the roller 345 will contact with the type wheels 322, 320 and 317 (Fig. 1) thereby causing the character of transaction, clerk's initial, and amount of the item of this particular transaction to be printed upon the record strip. This is caused by the arm 377 carrying the pin 357 that is engaged by the lever 364 and the pitman 359, which is moved downward by the roller 360 and the cam race 361 formed in the disk 362, and which gets its movement from the shaft 34 through the regular train of gears shown in Fig. 3.

Simultaneous with the printing on the record strip, above described, the transaction totalizer, which, it will be remembered is mounted upon the shaft 256 (Fig. 5), is turned to zero; that is, the amount that was left upon this counter for the previous transaction is cleared from said totalizer. This is accomplished by means of a clockwise movement of the segment 290, the teeth 289 of which engage the projections 288 of the disk 287, which, it will be remembered is fast upon the sleeve that carries the transaction counter wheels, and rotates the disk 287 and counter wheels counter-clockwise. The movement of the segment 290 is occasioned by the engagement of the teeth 292, integral with the segment 291, which is also integral with the segment 290, with the teeth 293 of the segment 294 which is rocked counter-clockwise by the disk 298 engaging the roller 297 carried by the arm 296 which, it will be remembered, is integral with the segment 294.

Simultaneous with the turning to zero of the transaction totalizer, above described, all displaced transfer arms 146 and transfer levers 169 (Fig. 7) that were tripped during the previous operation of the machine are restored to their normal position. This is accomplished by means of the cam race 198 (Fig. 20) formed in the disk 199 that engages an anti-friction roller 197 carried by the pitman 195, and causing said pitman to be moved forward, which, in turn, causes the arm 194 and the shaft 174 to be rocked in a counter-clockwise direction; so that the arms 192 (Fig. 7), which, it will be remembered are fast upon the shaft 174 and which carry the rod 193 (Figs. 1 and 7), will be rocked counter-clockwise so that rod 193 will engage the transfer levers 169, rocking said transfer levers clockwise so that the pawl 171 will be disengaged from the notch 185 and will engage the notch 172. This also causes the arms 187 (Fig. 7), through the connection of the link 190 with an arm 191 and an arm 189, which are fast upon the shafts 174 and 188, respectively, to be rotated in a counter-clockwise direction so that the rod 186 carried by the arms 187, will engage the transfer arms 146, thereby causing said arms to be disengaged from the V-shaped notches 160 of the arms 149 and to engage the other notch 150, as is shown in Fig. 7. After the transaction actuator was turned to zero, the pawl 261 (Figs. 7 and 15) were again locked in engagement with the pinion 260 of the transaction totalizer wheels 254 by means of the link 267, lever 270, pitman 274 and the cam race 277.

It will be remembered that the transaction which is now being recorded upon the machine is a charge account therefore the grand totalizer will not be engaged with the actuators. The mechanism for effecting this comes into play at this time. When the actuator 67 was set up by the lever 70 (Fig. 11), for a charge transaction, the roller 232 carried by the bell crank 230 remains in the shorter radial portion of the slot 233 thereby causing the link 226 to remain in the position shown in Fig. 11, which also holds the plate 219 in its normal position. At the proper time the arm 236 (Fig. 11) is rocked clockwise to engage the grand totalizer with the actuators. Since the plate 219 has not been moved the roller 237 carried by the arm 236, 130

simply slides idly in the slot 253 of said plate, and the grand totalizer will not be engaged with the actuators. The movement of this arm 236 is caused by the cam slot 120, 5 which engages the anti-friction rollers 119 carried by the pitman 116 and causes said pitman to be moved upward, which, it will be remembered, is pivotally mounted to the lever 114 that is integral with the arm 236. 10 At the proper time the counter wheels 524 (Fig. 1) of the transaction totalizer, the clerk's initial type wheel 416 and the transaction type wheel 415 and the date type wheels 410 and 411 are brought into 15 engagement with the amount actuators 59, the transaction actuator 67 and the clerk's initial actuator 71, by means of a pair of disks 286 (Figs. 1 and 15), in which is formed a cam race 285 that engages anti- 20 friction rollers 284 carried by parallel arms 282, which are integral with the plates 257 and 258. The cam race 285 causes the plates 257 and 258 to be rocked in a counter-clockwise direction so that the pinions 260, which, 25 it will be remembered, are fast to the sides of the transaction totalizer wheels 254 will be engaged with the teeth of the amount actuators so that when said actuators are restored to their normal positions the 30 amount which was set thereon will be put upon said totalizer wheels. After the grand totalizer has been either engaged or left disengaged from the actuators and after the record had been printed upon the 35 record strip, the alining pawls 80 and 87 are unlocked so that said actuators may be restored to their normal positions.

The actuators 59, 67 and 71 are restored to their normal positions by means of the 40 shaft 124 (Figs. 1, 7, 11 and 22), which is carried by a pair of parallel levers 125 and 126 that are rotatably mounted upon the shaft 34. These levers are rocked in a clockwise direction by means of the links 45 128 and 131 that are pivotally fastened to said levers and are controlled by the pairs of double plate cams which are formed by two plates each 136 and 137 and 142 and 143 as illustrated in Figs. 2 and 22. These 50 cams are fast upon the cam shaft 38, and when said shaft is revolved in a clockwise direction (Fig. 22) said links will be moved rearward thereby causing the levers 125 and 126 to be rocked in a clockwise direction 55 a distance sufficient to cause the shaft 124 to engage the forward end 145 of slots 144, which, it will be remembered are formed in each of the amount actuators 59 and also the clerk's initial actuator 71 and 60 the transaction actuator 67, thereby causing said actuators to be restored to their normal or home positions. During the restoration of said actuators the clerk's initial, character of transaction, and the 65 amount of said item of this transaction, will

be put upon the wheels 415 and 416 (Fig. 1) and the transaction totalizer counter wheels 254 (Fig. 1). As the grand totalizer was not engaged for this charge transaction nothing will be accumulated thereon. 70

At the proper time, and after the restoration of the actuators as above described, the transfer takes place in the grand totalizer and also the transaction totalizer, and is accomplished by means of the pins 160 75 and 183 (Fig. 7), which it will be remembered, engage the portions 161 and 184 of the transfer arms 146 and transfer lever 169 respectively. It will be understood that this pin engages these transfer arms and 80 transfer levers only when one or more of the counter wheels have passed from 9 to zero. The engagement of these pins 150 and 183 causes the transfer arms 146 and the transfer levers to be tripped, thereby 85 allowing the actuators to move one extra step which will add one to the wheel of the next highest denomination. Simultaneous with the transfer movement the ribbon mechanism (not shown in these drawings as it is no part of this invention) is 90 operated to feed the ribbon 355 (Fig. 7).

At the proper time and after the transfers have taken place the lever 236 is rocked in a counter-clockwise direction by the pitman 116 and brought to its normal position as shown in Fig. 11. Should this transaction have been a cash or received on account transaction this restoring of the lever 236 would have disengaged the grand totalizer. 95

At the proper time, and after the amount has been accumulated upon the transaction totalizer, the pawls 261 (Figs. 7 and 15), are again locked in engagement with the pinion 260 of the said totalizer wheels. 100 After these totalizer wheels have been locked the said totalizer is disengaged from the actuators by means of the arms 282 rollers 284 and cam race 285, which causes said arms and the plates 257 and 258 to be 110 rocked in a clockwise direction, which will disengage the totalizers from the actuators.

During the last part of the cycle of cam shaft 38 the pin 402 (Fig. 11) engages the portion 400 of the lever 397 thereby causing said lever to be rocked in a clockwise direction a distance sufficient to cause the pawl 398 to be disengaged from the notch 399 and to engage the notch 403. This causes the bail 395 carried by the lever 397 and an arm 120 396 to engage the upper portion of the projection 123 that is integral with the alining pawl 87, which engages the clerk's initial actuator. This prevents the clerk from operating the clerk's initial lever until he has 125 operated the slip printer lever which unlocks said pawl from the clerk's initial actuator.

After the clerk has operated the crank handle two revolutions he will now set up 130

the amount of the next item, which in this case was potatoes and was \$3.50. This he will set up by the manipulation of the amount levers 66 (Fig. 21) identically the

5 same way as he did for the first item. The crank handle 40 is then moved slightly in the inoperative direction to release said handle as previously described. The handle is then given two revolutions in the operative 10 direction, and the mechanism goes through identically the same movement as above described. He then has three more items to record upon the machine; one was eggs, at 60¢; flour, at \$18.00; and another was meat, 15 at \$2.00. For each of these items the crank handle must be given two complete revolutions.

The autographic feature for the sales slip may now be utilized and clerk "A" will write 20 his initials opposite the word "clerk"; "Mr. Richard Roe" on the second line; "sold to" and Mr. Roe's address on the third line; and then enter the items and amounts thereof sold to this customer.

25 After having recorded all of the five above mentioned amounts upon the machine, and made the notation upon the sales slip, the clerk operates the sales slip lever 443 (Fig. 5) by pulling said lever forward and downward as far as it will go. When said lever is in nearly a horizontal position the hooks 452 (Fig. 5) and 453 (Fig. 7) engage the rollers 454 (Figs. 1 and 5). As soon as the hooks 452 and 453 engage the rollers 454 the 30 clerk exerts an extra downward pressure upon the lever 443 which, so to speak, "breaks" said lever from the plates 257 and 258 thereby causing the type upon the peripheries of the transaction totalizer wheels, 35 the type upon the clerk's initial and transaction type wheel, and also the date, to be printed upon the slip. The amount which is printed upon the slip is illustrated in Fig. 18, and is \$24.40, which is a total amount of 40 the five items which were bought by Mr. Richard Roe.

The downward movement of the lever 443 causes the shaft 259 to be rocked in a clockwise direction (Figs. 5, 7, and 11). The 50 clockwise rotation of this shaft 259 will cause the segment 519 (Fig. 7) to be rocked clockwise, so that the teeth integral therewith will rock the pinion 514 and the snail cam 516 in a counter clockwise direction, 55 which causes the cylinder 490 and the electro 497 thereon to be revolved in a counter-clockwise direction so that the characters upon the electro 497 will be printed upon the slip. This movement of the cylinder 60 causes the consecutive number to be printed upon the sales slip. The rocking of the shaft 259 also causes the segmental plate 511 (Fig. 21) to be rocked clockwise, thereby causing the roller (Figs. 7 and 21) to be 65 brought in engagement with the electro 497

so that the slip paper which passes between the electro 497 and the roller 508 will receive a good impression, and also to help to feed said slip.

The clockwise rotation of the shaft 259 70 also causes a segment 543 (Fig. 7) to be rocked in a clockwise direction, whereby the rack 544 and plate 548 will be moved rearward, causing the pinions 550 and 552 to be revolved in a counter-clockwise direction, 75 which in turn causes the pinion 553 and snail cam 559 to be revolved in a clockwise direction. This causes the disks 538 to be revolved in a clockwise direction so that the pins 541 upon the peripheries of 80 said disks will feed the slip paper, through the engagement of said pins with the holes 542 in said paper, forward and out of the front of the machine so that it may be torn off by the clerk. When the clerk tears off 85 the paper he will have a slip which is exactly like the sample illustrated in Fig. 18. The one shown in Fig. 18 represents the original as it will be remembered the slips are issued in duplicate, the original being 90 given to the customer and the duplicate being filed in a credit file or any other suitable filing device which forms a part of the system of the store wherein this machine is being used. 95

The clockwise movement of the shaft 259 also causes the pitman 405 (Fig. 11), through the engagement of the cam 408 with the roller 407, to be moved upward to its normal position, which causes the lever 100 397 to be rocked in a counter-clockwise direction thereby disengaging the bail 395 from the upper portion of the projections 123 of the pawl 87. This unlocks the pawl 87 from the clerk's initial actuator so that 105 the clerk's initial lever may be operated for a subsequent operation of the machine.

The movement of this shaft 259 also causes the pitman 311 (Fig. 5) to be moved rearward thereby causing the segment 294 110 to be rocked in a clockwise direction, which rocks the segments 290 and 291 counter-clockwise, thereby restoring these segments to their home or normal positions as shown in Fig. 5.

The clockwise movement of the shaft 259 115 also causes the disk 315 (Fig. 5) to receive said movement, which raises the link 329, so that the arm 328 and shaft 147 (Figs. 5 and 12) will be rocked clockwise in order to 120 rock the pawl 325, so that the consecutive number will be advanced one.

The upward movement of the link 329 causes the portion 393 (Fig. 5) thereof to engage the pin 394, carried by the lever 388, 125 and causes said lever to be rocked counter-clockwise, so that the pawl 391 will be disengaged from the notch 390 and will engage the notch 389. The rocking of the lever 388 rocks the shaft 309 and the arms 383 (Fig. 130

11) and 384 (Fig. 7) a distance sufficient to cause the rod 385 to be positioned in front of the projections 386, integral with the actuators. This is the home position of the rod 385. In order to operate the machine again the clerk must first set the clerk's initial lever.

After the handle has been pressed down as far as it will go, it is released and the 10 spring 448 will cause said handle and the plates 257 and 258 to be rocked in a counter-clockwise direction and returned to their home or normal position. This will also cause the shaft 259 to be rocked counter-clockwise thereby restoring all of the cams and disks fast thereto to their home positions.

While the form of mechanism herein shown and described, is admirably adapted 20 to fulfil the objects primarily stated, it is to be understood that it is not intended to confine the invention to the one form of embodiment herein disclosed, for it is susceptible of embodiment in various forms all coming within the scope of the claims which follow.

What is claimed is:—

1. In a machine of the class described, the 30 combination of an item recording mechanism, a transaction recording mechanism, differentially adjustable actuators for setting the item recording and the transaction recording mechanisms, and independent means for operating each of said mechanisms.

2. In a machine of the class described, the 40 combination of an item printing mechanism, a total printing mechanism, differentially adjustable actuators for setting both printing mechanisms, means for actuating the item printing mechanism to enter each individual item, separate and independent means for actuating the total printing mechanism when all the items of a single transaction shall have been entered, and means for preventing the operation of the item printer during the operation of the total printer.

3. In a machine of the class described, the 50 combination of a printing mechanism for printing the several items of a transaction, another printing mechanism for printing the total of the items of the transaction, differentially adjustable actuators for setting up in both printing mechanisms the amounts to be printed, and separate and independent means for operating the printing mechanisms.

4. In a machine of the class described, the 60 combination of an item printing mechanism, a total printing mechanism, differentially adjustable actuators for setting both mechanisms, means for actuating the item printing mechanism, means for actuating the total printing mechanism, and automatically op-

erated means for clearing the total printing mechanism after each operation.

5. In a machine of the class described, the combination of item printing mechanism, a transaction totalizer, differentially adjustable actuators for setting the item printing mechanism and for accumulating the amounts of the items upon the transaction totalizer, means for operating the item printer, and separate and independent means 75 for recording the amount which is upon the transaction totalizer.

6. In a machine of the class described, the combination of item printing mechanism, a transaction totalizer, differentially adjustable actuators for simultaneously setting the item printing mechanism and for accumulating the amounts of the items upon the transaction totalizer, means for operating the item printer, and separate and independent means 80 for recording the amount which is upon the transaction totalizer.

7. In a duplicate recording machine, the combination of an item recorder, a transaction recorder, differentially adjustable actuators for setting the item recorder and for accumulating the sum of the items upon the transaction recorder, means for actuating the item recorder, means for actuating the transaction recorder, means for locking the transaction recorder during the operation of the item recorder, and means for locking the item recorder during the operation of the transaction recorder.

8. In a duplicate recording machine, the 100 combination of an item recorder, a transaction accumulator, manually adjustable differential actuators for setting the item recorder and for accumulating the items upon the transaction recorder, record material for receiving an impression from the item recorder, other record material for receiving an impression from the transaction recorder, means for actuating the item recorder, and means for actuating the transaction recorder.

9. In a duplicate recording machine, the 105 combination of an item recorder, a transaction accumulator, manually adjustable differential actuators for setting the item recorder and for accumulating the items upon the transaction recorder, record material for receiving an impression from the item recorder, other record material for receiving an impression from the transaction recorder, means for actuating the item recorder, means 110 for actuating the transaction recorder, means for locking the transaction recorder during operation of the item recorder, and means for locking the item recorder during the operation of the transaction recorder.

10. In a duplicate recording machine, the 115 combination of an item recorder, a transaction recorder, manually adjustable differential actuators for setting the item recorder and for accumulating the items upon the 120 transaction recorder.

transaction recorder, means for actuating the item recorder, a platen for holding the record material upon which the total of the transaction is to be recorded, and means for 5 moving the transaction recorder so that it may coöperate with the platen and record thereon the matter contained in the transaction recorder.

11. In a duplicate recording mechanism, the 10 combination of an item recorder, a transaction accumulator, manually adjustable differential actuators for setting the item recorder and for accumulating the data upon the transaction accumulator, record material 15 to receive the impression of the item recorder, a table upon which is displayed another sheet of record material upon which items may be written by the operator, and means for shifting the transaction accumulator 20 and to record the amount thereon upon the second sheet of record material.

12. In a machine of the class described, the combination of a transaction recording totalizer, differentially adjustable actuators 25 for entering item amounts into the totalizer, a platen for receiving recording material, means for effecting a relative movement between the platen and the transaction totalizer to record the data of the totalizer upon the 30 record material, and means for automatically restoring the transaction totalizer to zero.

13. In a machine of the character described, the combination of a transaction recording totalizer, differentially adjustable actuators 35 therefor, a platen for receiving record material, means for moving the transaction totalizer to engage the platen and record its data upon the record material, and means for automatically restoring 40 the totalizer to zero.

14. In a machine of the class described, the combination of a transaction printing totalizer, differentially adjustable actuators for entering items upon the totalizer, automatic means for moving the totalizer into 45 and out of engagement with the actuators for the entry of the items upon the totalizer, a platen for receiving recording material, means for moving the transaction printing 50 totalizer to engage the platen and record its data upon the record material, and means for automatically restoring the totalizer to zero.

15. In a machine of the character described, the combination of a transaction printing totalizer, manually adjustable differential actuators for accumulating 55 amounts upon the transaction recorder, a platen for receiving record material, means 60 for feeding the record material, means for moving the totalizer and for actuating the means for feeding the record material so that the material shall be fed and the data of the totalizer impressed thereon, and 65 means for restoring the totalizer to zero.

16. In a machine of the character described, the combination of a transaction printing totalizer, differentially adjustable actuators therefor, a platen for receiving record material, means for effecting a relative 70 movement between the totalizer and the platen for impressing the data of the totalizer upon the record material, and means for preventing the relative movement of the parts while the actuators are in engagement 75 with the totalizer.

17. In a machine of the character described, the combination of a transaction printing totalizer, manually adjustable differential actuators for actuating the totalizer, a platen for receiving record material, means for moving the totalizer to coöperate 80 with the platen so as to impress the data of the totalizer upon record material on the platen and automatic means for restoring 85 the totalizer to zero.

18. In a machine of the character described, the combination of a transaction printing totalizer, differentially adjustable actuators therefor, a writing table and a 90 printing platen adjacent each other for receiving record material, means for moving the totalizer to coöperate with the platen to impress on the record material the data of the totalizer, and means for restoring the 95 totalizer to zero after each printing operation.

19. In a machine of the character described, the combination of an item printer for recording the several items of a transaction, a transaction totalizing mechanism for accumulating the total of the several items of the transaction, a consecutive numbering device for numbering the transaction, and means controlled by the transaction totalizing 100 mechanism for actuating the consecutive numbering device.

20. In a machine of the character described, the combination of an item printer for recording the amounts of the individual 110 items of a transaction, a transaction totalizer for accumulating the amounts of the individual items of the transaction, differentially adjustable actuators for setting the item printer and for actuating the totalizer, 115 a consecutive transaction numbering device operating in conjunction with the item printer to print the number of the transaction adjacent the amount of each item of the transaction, and means controlled by the 120 totalizer for actuating the consecutive transaction numbering device.

21. In a machine of the character described, the combination with an item printer for printing the amounts of the individual items of a transaction, a transaction totalizer for accumulating the amounts of the individual items of the transaction, differentially adjustable actuators for actuating the item printer and for accumulating 125 130

the sum of the individual items upon the totalizer, a consecutive transaction numbering printer coacting with the item printer to indicate the number of the transaction to which the individual items belong, means for taking an impression of every item and of the number indicating the transaction to which the item belongs, and means controlled by the totalizer for shifting the consecutive numbering device.

22. In a machine of the character described, the combination of an item recording mechanism, a transaction totalizer, a consecutive transaction recorder, and means controlled by the totalizer for actuating the consecutive transaction recorder.

23. In a machine of the character described, the combination of an item printer for recording the amounts of the individual items which go to make up a transaction, a consecutive transaction numbering printer coöperating with the item printer for indicating the transaction to which each of the several items belongs so that the number 20 of the transaction is printed with each of the items of the transaction, a transaction totalizer for accumulating the amounts of the individual items of any given transaction, and means controlled by the totalizer 25 for shifting the consecutive numbering device.

24. In a machine of the character described, the combination of an item recording device for recording the separate items 35 of a transaction, a consecutive transaction numbering recorder for recording with each item the number of the transaction, a transaction recording totalizer for recording the total of the item or items of the transaction, 40 differentially adjustable actuators for actuating the item recorder and for accumulating upon the totalizer the amount or amounts of the item recorder, a platen for receiving record material, means for producing a relative motion between the recording totalizer and the platen so as to record on record material the data upon the transaction totalizer, and means under the control of the transaction printing mechanism 45 for shifting the consecutive numbering device.

25. In a recording machine, the combination of an item recorder for recording the items of a transaction, a transaction accumulating recorder for accumulating the amounts of the individual items of the transaction and for recording the sum of these amounts, a consecutive transaction numbering device operating in conjunction with the item recorder, means for causing the consecutive transaction numbering device to make a record in connection with the entry of each item of a transaction so as to indicate the number of the transaction to which 60 the item belongs, a second consecutive trans-

action numbering device operating in conjunction with the transaction recorder to record the number of the transaction, and means controlled by the transaction recorder for actuating both of the consecutive transaction numbering devices.

26. In a recording machine, the combination of an item recording mechanism for making a record of the item or items of a transaction, a transaction recording mechanism for accumulating the amounts of the items of the transaction and for recording the sum of these amounts, differentially adjustable actuators for setting up the amount of the items upon the item recording mechanism and for accumulating the amounts of the several items upon the transaction recorder, a consecutive transaction numbering device operating in conjunction with the item recording mechanism to indicate the 80 number of the transaction to which the individual items belong, means for recording the consecutive transaction number with the entry of each item of the item recording mechanism so that the record will show the 85 number of the transaction to which the item belongs, a second consecutive transaction numbering device operating in conjunction with the transaction recording mechanism to record the number of the transaction, and means controlled by the transaction recording device for actuating both of the consecutive transaction numbering devices.

27. In a recording machine, the combination of an item recording mechanism for recording the separate items of a transaction, a totalizing transaction recording mechanism for accumulating the amounts of the several items of the transaction and for recording the sum of these amounts, a consecutive transaction numbering device operating in conjunction with the item recording mechanism to indicate the number of the transaction to which the separate items belong, means for making a record by the consecutive transaction numbering device for each of the items of the transaction so as to indicate the transaction to which the item belongs, a second consecutive transaction numbering device operating in conjunction with the transaction recorder to record on a second record the number of the transaction, means controlled by the transaction recording mechanism for actuating both of the consecutive transaction numbering devices, and means for preventing the operation of the consecutive transaction numbering device which coacts with the item recording mechanism until the transaction recording mechanism has been actuated to make a record.

28. In a machine of the character described, the combination of an item recording mechanism for recording the individual items of a transaction, a transaction totalizing mechanism for accumulating the total 130,

- of the individual items of a transaction, a consecutive numbering device operating in conjunction with the item recording mechanism for numbering the individual items 5 with the number of the transaction, and means controlled by the transaction totalizing mechanism for actuating the consecutive numbering device so as to change the numbering device with each transaction.
- 10 29. In a machine of the character described, the combination of an item printer for recording the amounts of the individual items of a transaction, a transaction recording totalizer for accumulating the amounts 15 of the individual items of the transaction, differentially adjustable actuators for setting the item printer and for actuating the totalizer to accumulate thereon the sum of the items, means for operating said totalizer 20 to record the amount of the transaction, means for compelling the completion of the entry of the item before the totalizer can be operated to record any transaction, a consecutive transaction numbering device operating 25 in conjunction with the item printer to record with each item the number of the transaction to which it belongs, a second consecutive transaction numbering device operating in conjunction with means for 30 compelling the completion of the entry of the item before the transaction recording totalizer can be operated, and means for compelling a record to be made from the transaction recording totalizer before the transaction 35 numbering device can be operated.
30. In a machine of the character described, the combination of an item recording device for recording the separate items of a transaction, a consecutive transaction 40 number recorder for numbering each item with the number of the transaction, a transaction recording totalizer for recording the total of the transaction, means for operating the transaction number recorder to number 45 each item of the transaction so as to indicate the transaction to which the separate item belongs, means for operating the transaction recording totalizer after the items of a transaction shall have been entered, means for 50 compelling the completion of the entry of an item before the transaction totalizer can be operated to make a record, and means for operating the transaction number recorder after the record has been made by the transaction 55 numbering mechanism.
31. In a machine of the character described, the combination of an item printer for recording the amounts of the separate items of a transaction, a transaction totalizer 60 for accumulating the amounts of the separate items of the transaction, differentially adjustable actuators for setting the item printer and for accumulating the items upon the totalizer, a consecutive transaction numbering device for numbering the separate 65 items of the transaction, means for preventing the operation of the transaction numbering device until the items of the transaction shall have been entered and a record made of the total thereof. 70
32. In a machine of the character described, the combination of an item recorder for recording the items of a transaction, a consecutive transaction numbering device, differentially adjustable actuators for setting the item recorder, means for taking an impression of both the item recorder and the transaction numbering device with the entry of each item of a transaction, and means for shifting the transaction numbering device 75 after each transaction. 80
33. In a machine of the character described, the combination of an item printer for recording the amount of each item of a transaction, a consecutive transaction numbering printer coöperating with the item printer for indicating the transaction to which each of the several items belongs so that the number of the transaction is printed with each of the items of the transaction, 85 differentially adjustable means for setting the item printer for each item, means for simultaneously taking an impression of the item printer and of the consecutive transaction numbering device as each item is entered in the machine so that each item can be identified with the transaction to which it belongs, and means for shifting the transaction device after every transaction. 90
34. In a machine of the character described, the combination of an item printer for recording the amount of the separate items of a transaction, a consecutive transaction numbering printer coöperating with the item printer for indicating the transaction to which each of the several items belongs so that the number of the transaction is printed with each of the items of the transaction, differentially adjustable means 95 for setting the item printer for each item, means for simultaneously taking an impression of the item printer and of the consecutive transaction numbering device after the entry of each item in the machine so that each item can be identified with the transaction to which it belongs, means for preventing the operation of the transaction numbering devices during the entry of an item and the making of a record thereof so that the consecutive transaction numbering 100 device can be shifted, only after the item and its transaction number have been recorded and means for shifting the consecutive transaction numbering device. 105
35. In a machine of the class described, the combination of item printing mechanism, total printing mechanism, means controlled by the item printing mechanism for compelling an operation of said item printing mechanism before the total printing 110 115 120 125 130

mechanism can be operated to record the total and for preventing successive operations of said total printing mechanism, and means controlled by the total printing mechanism for restoring the first means to normal position.

36. In a machine of the character described, the combination of an item recording mechanism for recording the amount of 10 the item or items of a transaction, a total recording mechanism for recording the amount of the item or the sum of the items of the item recording mechanism, a normally locked cash drawer, means controlled by the 15 total recording mechanism for releasing the cash drawer.

37. In a machine of the character described, the combination of an item printing mechanism for printing the amount of the 20 item or items of a transaction, a total printing mechanism for printing the amount of the item or the sum of the items of the item printing mechanism, a normally locked cash drawer, means controlled by the total printing mechanism for releasing the cash drawer.

38. In a machine of the character described, the combination of item recording mechanism for recording the amount of the 30 item or items of a transaction, a transaction totalizer for recording the sum of the items of the transaction, a normally locked cash drawer, means controlled by the totalizer for releasing the cash drawer, and means for 35 preventing operation of the releasing means until the transaction shall have been recorded.

39. In a machine of the character described, the combination of an item printer 40 for recording the item or items of a given transaction, a total printing mechanism for recording the sum of the items of the transaction, a platen to receive record material, means coöperating with the platen for im- 45 pressing upon record material the data on the total printing mechanism, a cash drawer, means controlled by the total printing mechanism for releasing the cash drawer whenever a record of the transaction total 50 printing mechanism is taken.

40. In a machine of the class described, the combination of item recording mechanism, transaction recording mechanism,

means for setting the item recording mechanism and for entering the amount of the 55 items in the transaction recording mechanism, means for compelling completion of the entry of an item before the transaction recording mechanism can be operated to make a record, a cash drawer, and means 60 controlled by the transaction recording mechanism for releasing the cash drawer so that the cash drawer can be opened only when a record of the transaction is made.

41. In a machine of the class described, 65 the combination of item printing mechanism, transaction printing mechanism, differentially adjustable actuators for setting the item printing mechanism and for entering the items in the transaction printing mechanism, 70 means for compelling completion of the entry of an item before the transaction printing mechanism can be operated to print a record of the transaction, a normally locked cash drawer, a latch for releasing 75 the drawer, and means actuated by the transaction printing mechanism for operating the drawer latch, so that the drawer can be opened only when a record of the transaction is made.

42. In a machine of the class described, the combination of an item printer for printing the amounts of the item or items of a transaction, a transaction totalizer for accumulating the sum of the items of the transaction, differential adjustable actuators for setting the item printer and for accumulating the items upon the transaction recorder, a platen for receiving record material, means coöperating with the platen for printing on 80 record material the amount accumulated by the transaction totalizer during any one transaction, means for compelling completion of the entry of an item before the transaction printing mechanism can be operated to print a record of the transaction, a normally locked cash drawer, means controlled by the transaction printing mechanism for releasing the cash drawer when 85 printing a record of the transaction so that 90 the cash drawer may be opened only when a record of the transaction is made, and means for clearing the transaction totalizer 95 after the printing of each transaction.

In testimony whereof I affix my signature. 105
HAAKON A. MARTIN.
